UNITED STATES PATENT OFFICE.

HUGH D. MACPHERSON, OF SUMMIT, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed August 15, 1921. Serial No. 492,229.

To all whom it may concern:

Be it known that I, HUGH D. MACPHERSON, a citizen of the United States, residing at Summit, in the county of Union, State of New Jersey, have invented certain new and useful Improvements in Telephone Systems, of which the following is a full, clear, concise, and exact description.

This invention relates to improvements in telephone systems and has particular reference to a system wherein the signals for a plurality of toll lines extending between widely separated offices are transmitted over a signaling path common to said toll lines.

It has been heretofore proposed to employ a signaling path common to a plurality of toll lines and extending between distant offices with means at each end of said path for transmitting therover supervisory signals characteristic of each individual line and incident to the establishment and release of a connection over said line. In systems of this character it has been necessary for the outward operator at an initiating office to communicate with the inward operator at a distant or incoming office to verbally inform her of the number of the wanted line, whereupon said inward operator proceeds to complete the connection, usually through a toll switching operator.

An object of the present invention is to provide a system of the above character wherein the necessity of the outward operator verbally communicating the number of the wanted line to the incoming operator is eliminated.

In accordance with this object use is preferably made of a call indicator positioned before the incoming operator and operable, in response to the registration of a call by the outward operator and consequent actuation of signal transmitting and receiving means, to indicate the number of the line wanted, whereupon the incoming operator may then proceed to complete the connection.

Another object is to provide means whereby the signals individual to each line, which are employed for supervising a connection over said line and those for controlling the operation of the call indicator, may be transmitted over the same signaling path which is common to a plurality of lines.

Other objects will appear in the course of the following description when taken in

connection with the accompanying drawings, Figs. 1 to 10 of which, when arranged in accordance with Fig. 11, illustrate a preferred embodiment of the inventive idea.

General description of operation.

Briefly, the invention comprises a plurality of toll lines, similar to the line L, extending between an outward operator at one office and an incoming operator at a distant office. The outward operator is provided with a number of cord circuits, such as indicated at A, any one of which may be employed to connect a calling subscriber's line with one of the toll lines. At the outward operator's position there is provided a set of keys operable to register the office, numerical and station designations of a wanted line. These keys may be of any preferred type well known in the art and upon actuation thereof by the outward operator certain relays in the cord register shown in Fig. 1, corresponding to the operated keys, are energized to prepare circuits for the energization of similar relays in the line register illustrated in Figs. 5 and 6. After registering the number of the wanted line on the cord register, the outward operator then connects the cord A with an idle toll line L, whereupon certain operations take place which result in the connection of the cord and line registers and the energization of relays in the latter in accordance with the condition of relays in the former. The codes for the various office, numerical and station designations of the called line, which consist of impulses of different polarities determined by the condition of the line register relays, are now stored in the line register and await the transmission of supervisory impulses to the distant office, which light a guard lamp thereat individual to the toll line taken for use, to inform the incoming operator that a call is awaiting attention on said line. These supervisory impulses, which are individual to the line L, are transmitted immediately upon connection of the cord A with the line L and while the line register relays are being operated.

The incoming operator, in response to the actuation of the signal for line L, operates an assignment key which results in the transmission of a code of impulses to the outward office followed by a repetition of this code from the outward to the inward office to

associate the incoming operator's call indicator with the line register and the common signaling path over which all impulses are transmitted. Eight series of code impulses

5 are now transmitted in accordance with the condition of the register relays in the line register, these series corresponding to the three office, four numerical and one station designations of the wanted line. In response 10 to these series of impulses the call indicator before the incoming operator is actuated to display, by means of lamps, the number of the called line.

The incoming operator now secures an assignment of a toll switching trunk, such as 15 H, from the toll switching operator and at the same time informs her of the number wanted. The latter operator then connects the toll switching trunk with the called subscriber's line. The incoming operator connects the line L with the toll switching trunk which results in the release of the call indicator and the transmission of the individual code of line L to the outward office to light a 20 guard lamp thereat in response to which the outward operator actuates the ringing key to signal the wanted subscriber. When the call is answered a code of impulses is again transmitted to the outward office to extinguish the guard lamp after which the outward operator no longer actuates the ringing key.

At the termination of a conversation the release of the connection is effected by the 35 called subscriber replacing his receiver upon its switch hook, whereupon a code of impulses is transmitted to the outward office to again light the guard lamp to give the outward operator the disconnect signal. This 40 operator then disconnects the cord circuit A from the toll line L which causes the transmission of a code of impulses to the inward office to simultaneously light the guard lamps before the incoming and toll switching operators who then restore the circuit to normal by disconnecting the line L from the trunk H and said trunk from the called subscriber's substation circuit, respectively.

At any time during the conversation the 50 called subscriber may recall the outward operator by moving the switch hook up and down. Codes of impulses are transmitted from the inward to the outward office and their reception at the latter office causes apparatus to function to flash the guard lamp before the outward operator who thereupon connects her head set to the line.

If at the time of establishing a call the toll switching operator finds the wanted line 60 busy, she inserts the plug of trunk H into a busy flash jack. This operation causes the guard lamp before the outward operator to flash and upon connecting her head set to the line she receives a distinctive tone indicating a busy condition on the line wanted.

The release of the connection is then effected as previously referred to.

Detailed description of operation.

It is believed that the invention will now 70 be fully understood from the following detailed description of the operation of establishing a connection from an outgoing operator at one office over an idle toll line L to a called subscriber, whose substation is shown 75 in Fig. 7 and located in a distant office. A calling subscriber may be connected to the outgoing operator in any manner well-known in the art. Since this operation forms no part of the present invention, the apparatus 80 for making this connection is not shown in its entirety, only a portion of the outgoing operator's cord circuit A, which is employed to connect to the calling subscriber's line, being 85 illustrated.

Operator registers number of called line in cord register circuit.

Upon ascertaining the number of the called subscriber's line from the calling subscriber, the outgoing operator first proceeds to set up this number on the cord circuit register illustrated in Figs. 1 and 2. It will be assumed that the office designation of the wanted line is represented by the letters 90 WAL and the station designation of said line by the letter M. The register relays are arranged in groups and those for the office designations are indicated by the numerals 114 to 125, while relays for station 100 designations are indicated by the numerals 126 to 129. The relays of the register representing the number digits of called lines have been omitted for purposes of economy 95 in space and description, but it will be understood that these number relays operate in the same manner as the office and station relays. The operator first depresses the key 9, which corresponds to the first letter of the office designation, whereupon an operating 105 circuit is established for register relay 116 of the first group, which circuit extends from ground through the winding of relay 100, the right hand alternate contact of key 9, the right hand normal contact of key 6, 110 the left hand normal contact of key 5, the lower normal contact of the transfer relay 102 individual to the first group of register 115 relays, and the lower winding of relay 116 to grounded battery. An operating circuit is also established for relay 117 of the first group, which circuit extends from ground, 120 through the winding of relay 100, left hand alternate contact of key 9, the upper normal contact of relay 102, and the lower winding of relay 117 to grounded battery. Relay 100 is also energized in either of these 125 circuits, and in closing its contact establishes a circuit for relay 103 extending from grounded battery through the winding of 130

said relay, the lower normal contact of relay 101, and thence to ground through the contact of relay 100. Relay 103 energizes to close a circuit through its contact, the windings of relays 102 and 101 in series, and the contact of relay 113 to ground. Relays 101 and 102 do not energize in this circuit since they are short-circuited by the ground connected to contact of relay 100, and extending through the lower normal contact of relay 101, and contact of relay 103. Relays 116 and 117, upon energization, are locked up through their upper windings and contacts to ground at the contact of relay 113.

10 The operator now releases the key 9, whereupon relay 100 releases to remove the short-circuit from the windings 101 and 102, and these relays thereupon energize over the circuit extending to ground at the relay 113.

15 To transfer the conductors extending from the various keys of the operator's set to the normal contacts of the second group of transfer relays 104 and 105. The operator next depresses key 2 and again establishes a circuit for relay 100 and register relay 119 of the second group, said circuit extending from ground through the winding of relay 100, the left hand alternate contact of key 2, the lower alternate contact of relay 101, the middle normal contact of relay 104 and the lower winding of relay 119 to grounded battery. Relays 100 and 119 energize, and the latter relay locks through its upper winding and contact to ground at the contact of relay 113. The energization of relay 100 now establishes a circuit for relay 106, extending from grounded battery, through the winding of said relay, the lower normal contact of relay 104, the upper alternate contact of relay 102, and the contact of relay 100 to ground. Relay 106 energizes, and through its contact closes a circuit in series, through the windings of relays 104 and 105 to ground at the contact of relay 113, but, as before described in connection with relays 101 and 102, relays 104 and 105 are short-circuited as long as relay 100 remains operated. Upon the release of key 2, relay 100 releases to remove this short-circuit, and relays 104 and 105 thereupon energize. Relay 106 locks up in the circuit described for relays 104 and 105. The conductors leading from the keyboard are now extended through the alternate contacts of transfer relays 101, 102 and 104, 105 to the normal contacts of relays 107 and 108. Upon the depression of the key 5, corresponding to the third letter of the office designation, relays 100 and 124 are operated over a circuit extending from ground, through the winding of relay 100, the left hand alternate contact of key 5, the lower alternate contact of relays 102 and 105, the lower normal contact of relay 108 and the lower winding of relay 124 to battery. Re-

lays 100 and 124 energize, and the latter relay locks through its upper contact to ground at the contact of relay 113. The energization of relay 100 establishes a circuit for relay 109 extending from grounded battery through the winding of relay 109, the lower normal contact of relay 107, the upper alternate contacts of relays 105 and 102, and the contact of relay 100 to ground. The energization of relay 109 establishes a circuit for relays 108 and 107 in series to ground at the contact of relay 113, but said relays 108 and 107, as before described in connection with the other transfer relays, are short-circuited until relay 100 releases, whereupon said relays energize in the locking circuit for relay 109. The setting up of the office designation is now completed, and the operator then proceeds to depress keys corresponding to the number digits of the called line. In response to the successive actuation of these keys, the number register relays and corresponding transfer relays which have been omitted from the drawing, are operated in the same manner as described for the office register relays. The operator then completes the registration of the called line by actuating the key 6, which corresponds to the station designation of said line, whereupon relays 100, 126 and 128 will operate over circuits which will be obvious from an understanding of the description of operation of the other register relays. Relay 112 also energizes upon the operation of relay 100 over a circuit extending through the lower normal contact of relay 110 and the upper alternate contacts of relays 108, 105 and 102. When relay 100 releases in response to the restoration of the key 6, relays 110 and 111 are energized in series with relay 112. The operation of transfer relay 111 connects battery through its alternate contact to the winding of relay 200, but this relay does not energize until the line register (Fig. 6) and apparatus associated with the toll line are in condition to receive impulses from the cord register, which occurs after the plug 203 of the cord circuit A is inserted into the jack 300 of the idle toll line L, as will be more fully described hereinafter. Register relays corresponding to digits in the wanted line are now operated and locked, and transfer relays individual to the groups of register relays are also energized.

100 Should the operator at any time desire to erase the registration made, she may do so by actuating the wipe-out key 130, which closes an obvious circuit for relay 113. The operation of this relay removes ground from the contact thereof, and thus opens the holding circuits for such transfer relays as have been operated and the locking circuits of the register relays and of relays individual to said transfer relays. The apparatus is

thereby restored to normal, and the operator may then proceed to again register the called number.

5 Operator connects cord circuit A to idle toll line L.

The operator having completed the registration of the called line, inserts a plug 203 of the cord circuit A into jack 300, whereupon a circuit is established for relays 201 and 301, extending from grounded battery, through the windings of relays 201 and 202, sleeve contacts of plug 203 and jack 300, and winding of relay 301 to ground. Relays 201 and 301 energize in this circuit, but relay 202 being marginal does not operate at this time. The energization of relay 301 establishes an obvious circuit for the busy signal magnet 302, which operates to indicate the busy condition of the toll line L. The operation of relay 201 closes an obvious energizing circuit for relay 204, which disconnects the tip of the cord from the operator's busy test circuit and closes the tip circuit through the front contact of relay 204. The cord circuit register now awaits the condition previously referred to in the line apparatus and register.

The insertion of the plug 203 into jack 300 and consequent energization of relay 301 establishes an obvious energizing circuit for relay 304. The opening of the normal contact of this relay removes ground from the terminal individual to the trunk line L, over which the wiper 400 of the rotary switch C passes. This switch is common to all of the toll lines in the group in which line L is located and is operated, as will presently appear, to engage wipers 400, 401, 402, 403, 404, 405 and 406 with terminals associated with the selected toll line. A plurality of link circuits, one of which is shown at D, are associated with switches such as C, and are employed for connecting the line circuit to the line register shown in Figs. 5 and 6 through wipers of a rotary switch E, which operates to preselect an idle line register. An idle link circuit D is preselected by means of a rotary switch F' common to a group of links serving all of the toll lines. Wipers 407 and 408 of said switch F' engage terminals individual to said idle link when a toll line in a group is taken for use. The energization of relay 304 also establishes a circuit from ground, through the right hand alternate contact of relay 304, the contact of relay 307, conductor 308, common to all the toll lines in the group, and winding of relay 409 to grounded battery. Relay 409 energizes and remains in this condition until switch C has been operated to step its wipers to engage the terminals individual to the line L. Upon energization of relay 409, a circuit is established from ground, through the contact of this relay,

wiper 407 and the preselected terminal engaged thereby, wiper 400 in its normal position, the normal contact of relay 410 and the contact and winding of stepping magnet 411 to grounded battery. A circuit is also closed through the winding of relay 410, but this relay is shunted by the first described circuit until wipers of switch C have engaged the terminals of the toll line. Another circuit is established for relay 413 by the energization of relay 409, extending from grounded battery, through the winding of this relay, wiper 407, and contact of relay 409 to ground. The effect of the latter circuit will presently be described. The circuit described for magnet 411 causes the switch C to step its wipers from their normal positions and engage terminals individual to other toll lines. As long as the wiper 400 engages the terminal individual to an idle line, ground will be found upon this terminal through the normal contact of relay 304 of said idle line, and circuits will be established to continue the operation of stepping magnet 411. It is to be here noted that if two toll lines in the same group are simultaneously taken for use, the switch C will stop up on the terminals of the first line encountered, and the second toll line must await the preselection of another link circuit similar to D and associated with a different switch C. Upon engagement of wiper 400 with the terminal to which ground has been removed by the energization of relay 304, a circuit is no longer established for magnet 411, and the switch thereupon comes to rest upon the terminals individual to the toll line L. The circuit through magnet 411 and winding of relay 410 to ground at the contact of relay 409 now becomes effective to energize relay 410, but magnet 411 will not energize in series with this relay. The energization of relay 410 completes an energizing circuit for relays 307 and 412, extending from grounded battery, through winding of relay 307, the left hand alternate contact of relay 304, wiper 400 and terminal engaged thereby, the alternate contact of relay 410, and the winding of relay 412 to ground. The energization of relay 307 in this circuit opens the operating circuit for relay 409, which thereupon releases to open the energizing circuits for relays 410 and 413, but before relay 409 can release, the energization of relay 412 establishes, through its middle contact, substitute holding circuits for relays 410 and 413. The operation of relay 412 also closes a circuit for stepping magnet 414 of switch F', through the wiper 408 thereof to step said wipers from the terminals individual to the busy link circuit, until wiper 408 encounters a terminal free from ground, whereupon switch F' comes to rest, and another link circuit is thereupon preselected. At the

time relay 413 is energized, relay 501 operates in a circuit extending from ground through the contact of relay 413, the winding of relay 501 and the contact and winding of stepping magnet 500 to grounded battery. The stepping magnet being in series with relay 501, does not operate in this circuit and the wipers of switch E remain on the terminals of the preselected register. 5 The energization of relay 501 establishes a circuit extending from ground, through the alternate contact of this relay, the wiper 502 and terminal engaged thereby, and the left hand winding of relay 510 to grounded battery. Relay 510 energizes to close an obvious circuit for relay 509. The closure of the middle contact of this relay provides a busy test so that the busy line register will not be taken for use by a switch similar to 10 switch E through another link circuit. The operation of relay 509 also closes a circuit extending from ground, through the left hand contact of relay 509, normal contact of slow release relay 511, wiper 507 and terminal engaged thereby, the left hand contact of relay 412 which is now operated, wiper 405 of switch C and terminal engaged thereby, the right hand normal contact of relay 309, and the winding of relay 303 to 15 grounded battery, causing the operation of the latter relay.

The line circuit and register are now in condition to receive impulses from the cord register circuit to operate the storing and transmitting relays of said line register. 20 The operation of relay 303 establishes parallel circuits through windings of relays 305 and 309 to ground at the contact of relay 301, but relays 305 and 309 are short circuited by the ground from the left hand contact of relay 509, which causes the energization of relay 303, and relays 305 and 309 therefore do not operate at this time. The operation of relay 303 also closes a circuit extending from ground, through the normal contact of relay 305, the right hand contact of relay 303, resistance 306, the sleeve terminals of jack 300 and plug 203, and windings of relays 202 and 201 in 25 series to grounded battery. Marginal relay 202 operates in this circuit, and the closure of the contact of this relay establishes an obvious energizing circuit for relay 205. The latter relay thereupon locks through its inner right hand contact to ground at the contact of relay 201. The operation of relay 205 closes the circuit extending from ground, through the outer left hand contact of said relay, the left 30 hand normal contact of relay 206, and the winding of relay 207 to grounded battery. Relay 207 operates to connect the tip and ring conductors of the cord circuit A to the conductors 208 and 209, which lead to contacts of relay 210. Conductors 208 and

209 are common to the various cord circuits similar to the cord A at the outward operator's position. The energization of relay 205 connects ground at the contact of relay 201, through the outer right hand contact of relay 205, the inner right hand normal contact of relay 206, to the winding of relay 200. Battery having previously been connected to relay 200 through the alternate contact of transfer relay 111, the relay 200 now energizes. Lamp 211 is also lighted at this time to indicate to the outward operator that the call which was registered on the various register relays is now being transmitted to the line register. 70

After the operation of relay 200, a circuit is closed for relay 212, following the engagement of the contact of the interrupter 213 with a grounded segment thereof, which circuit extends from grounded battery, 75 through the winding of relay 212, normal contact of relay 214, and the contact of relay 200 to ground through the interrupter 213. Relay 212 energizes, and the operation thereof establishes a circuit for relay 214, 80 extending from grounded battery, through the winding and contact of relay 212, winding of relay 214, the inner right hand normal contact of relay 206, the outer right hand contact of relay 205, and the contact of relay 201 to ground. Relay 214 is short-circuited through its normal contact, and the contact of relay 212 as long as the brush of interrupter 213 engages a 85 grounded segment. When a non-grounded segment is reached, relay 214 energizes, and relay 212 locks in the energizing circuit of relay 214. When the brush of interrupter 213 again reaches a grounded segment, ground is extended through the alternate 90 contact of relay 214, the right hand normal contact of relay 215, and the winding of relay 210 to grounded battery. Relay 210 energizes to connect the conductors 208 and 209 to the wipers 216 and 217 of switch B. 95 At the same time that relay 210 is energized, a circuit is established for the stepping magnet 218 of switch B, extending from grounded battery, through the winding of this magnet, the left hand normal 100 contact of relay 215, and from thence to ground over the circuit described for relay 210. The stepping magnet 218 energizes, but the stepping pawl thereof is so arranged that the wipers of switch B will not 105 be moved until the circuit for the stepping magnet is opened and said magnet released. 110

Transfer of record from cord register to line register.

In the description of the operation of the cord circuit register, it will be recalled that register relays 116 and 117 of the first group were energized, and relays 114 and 115 of said group remained inert. Under this con- 125

dition and with wipers 216 and 217 of switch B in their first positions, a circuit is established from ground, through the resistance 131 at relay 115, the normal contact 5 of this relay, wiper 216 and terminal engaged thereby, the left hand contact of relay 210, conductor 208, left hand alternate contact of relay 207, the alternate contact of relay 204, the tip contacts of plug 203 10 and jack 300, the inner left hand normal contacts of relays 305 and 309, wipers 406 and 508 and terminals engaged thereby, winding of relay 512, the middle normal contact 15 of transfer relay 600, and the right hand winding of register relay 602 to grounded battery. Relay 512 operates in this circuit, but due to the inclusion of the resistance 131 therein, relay 602 will not operate. Inasmuch as relay 114 is not operated, the 20 ground at its lower contact will not be extended through wiper 217 and conductor 209 to the ring contacts of the plug and jack 203 and 300, and from thence to the winding of register relay 603, and this latter relay 25 will therefore remain inert. The energization of relay 512 establishes a circuit for relay 601, extending from grounded battery, through the winding of relay 601, the upper normal contact of relay 600, and the 30 contact of relay 512 to ground. Relay 601 operates, and through its contact closes a circuit through the winding of relay 600, and the right hand contact of relay 509 to ground, but relay 600 does not energize since 35 it is short-circuited by the ground at relay 512, through the upper normal contact of relay 600, and the contact of relay 601. When the brush of interrupter 213 next engages an ungrounded segment, relays 210 40 and 512 and magnet 218 release. The release of relay 512 removes the short-circuit for relay 600, which thereupon energizes and locks in series with relay 601. The restoration of the magnet 218 steps the wipers of 45 switch B to position 2.

When the brush of interrupter 213 again connects ground to the contact of relay 200, relay 210 and magnet 218 again operate. Register relays 116 and 117 are now associated, respectively, with the tip and ring contacts of plug 203 through wipers 216 and 217 in position 2. The operation of relay 116 establishes a circuit from ground, through the lower alternate contact of relay 116, wiper 216, and from thence over the 50 previously described circuit through the tip contacts of plug 203 and jack 300 as far as the middle normal contact of transfer relay 600. This relay being now energized, the 55 circuit is extended through the middle alternate contact of said relay, the middle normal contact of transfer relay 604, and the right hand winding of register relay 603 to 60 grounded battery. Since the resistance 132 at relay 116 is not included in this circuit, both relays 512 and 606 will operate. Relay 606 locks through its left hand winding and contact to ground at the right hand contact of relay 509. It will be recalled that relay 117 is also operated, and a circuit will 65 therefore be established extending from ground, through the lower contact of relay 117, wiper 217 in position 2, the right hand contact of relay 210, conductor 209, right hand alternate contact of relay 207, ring 70 contacts of plug 203 and jack 300, outer left hand normal contacts of relays 305 and 309, wipers 404 and 506, the lower alternate contact of transfer relay 600, the lower normal contact of relay 604, and the winding of relay 607 to grounded battery. Relay 607 energizes and locks through its left hand contact to ground at the right hand contact of relay 509. The operation of relay 512 in the 75 circuit for relay 606 closes a circuit for relay 605 extending from grounded battery, through the winding of relay 605, the upper normal contact of relay 604, the upper alternate contact of relay 600, and contact of relay 512 to ground. Relay 605 energizes and 80 locks in a circuit through its winding and contact, the winding of relay 604, and from thence to ground at the right hand contact of relay 509. Relay 604 does not operate 85 in this circuit due to its being shunted by the ground at relay 512 while this relay remains operated. Upon the next release of relay 512 at the time that the brush of interrupter 213 next engages a non-grounded 90 segment, the short-circuit for relay 604 is 95 removed, and this relay operates in series with relay 605. It will thus be seen that the engagement of wipers 216 and 217 with two associated contacts is necessary to 100 convey the conditions existing at the lower contacts of the cord register relays in the first group. Upon the engagement of the brush of interrupter 213 with the next non-grounded segment, which results in the second release of relay 512 to remove the short-circuit from relay 604, relay 210 and magnet 105 110 218 also release, whereupon switch B is stepped to engage its wipers with the third contacts.

The second group of cord register relays, 115 of which relay 119 is energized, are now associated with the conductors 208 and 209. The operation of relay 119 disconnects resistance 133 from the third terminal, upon which wiper 216 is now resting. Ground is connected directly to the alternate contact of relay 119 through wiper 216, and from thence, after relay 210 is again energized in 120 response to the engagement of the brush of interrupter 213 with a grounded segment, over the previously described circuit through the tip contacts of the plug and jack, as far as the middle normal contact of relay 604. This relay now being energized, the circuit 125 is extended through the middle alternate 130

contact of relay 604, the middle normal contact of relay 608, and the right hand winding of relay 610 to grounded battery. Relays 610 and 512 operate in this circuit, 5 and the former locks through its left hand contact to ground at the right hand contact of relay 509. The operation of relay 512 establishes a circuit for relay 609, through the upper alternate contacts of relays 600 10 and 604, and the normal contact of relay 608. Relay 609 energizes and locks through its contact and the winding of relay 608 to ground at the right hand contact of relay 509. Relay 608 does not energize in 15 this circuit for the same reason referred to with respect to relays 600 and 604. Inasmuch as relay 118 of the second group of cord register relays is not operated, the ground at the lower contact of said relay 20 will not be extended through wiper 217 over the ring contacts of the plug and jack to relay 611, and this latter relay will therefore remain inert. At the next interruption 25 of the ground connection at interrupter 213, relay 210 and magnet 218 again release, and wipers of switch B are stepped to position 4. The relays 120 and 121 are now associated with wipers 216 and 217. Relay 512 again releases to remove the short-circuit 30 for relay 608, which energizes in series with relay 609.

Upon the next operation of relay 210 and magnet 218 in response to the continued rotation of interrupter 213, a circuit 35 is established from ground, through the resistance 134, the normal contact of relay 120, wiper 216 in position 4, and from thence over the previously described circuit through the tip contacts of the plug and jack winding of relay 512, middle alternate contacts of relays 600, 604 and 608, middle normal contact of relay 612, and the right hand winding of relay 614 to grounded battery. Relay 614 is not energized in this circuit 40 due to the inclusion of the resistance 134, but relay 512 energizes to establish an energizing circuit for relay 613, through the upper alternate contacts of relays 600, 604 and 608, and upper normal contact of relay 612. Relay 613 locks in series with the winding of relay 612, but the latter relay does not energize due to the short-circuit established by relay 512. Relay 121 is not energized, and therefore ground will not be 45 connected to the ring contact of the plug and jack, so that relay 615 will fail to operate. The interrupter 213 next causes the release of relays 210 and 512, and the magnet 218, with the result that the wipers 50 of switch B are stepped to position 5 to associate the third group of cord register relays with wipers 216 and 217. The operation of successively associating the various groups of cord register relays with the mechanism of the line register causes the

operation of the remaining transfer relays 616, 620, 624 and 628 and associated relays 617, 621, 625 and 629 in the same manner as described in connection with other similar relays. Certain combinations of register relays 618, 619, 622, 623, etc., and register relays individual to the number digits which have been omitted from the showing, are also operated or remain inert in accordance with the condition of relays in corresponding groups in the cord register circuit. Bearing in mind that relay 124 of the third group, and relays 126 and 128 of the last group are energized, it will be apparent that relays 622, 627 and 630 will energize 80 and lock, and relays 618, 619, 623, 626 and 631 will remain inert. 75

After the potentials at the last group of cord register relays have been transmitted to the line register, and relays 629 and 630 have operated, relays 210 and 512 and magnet 218 release due to the engagement of the brush of interrupter 213 with a non-grounded segment, and relay 628 energizes in response to the release of relay 512. The release of magnet 218 now steps the wipers of switch B to position 17, and inasmuch as the seventeenth and succeeding positions of wipers 216 and 217 are not connected to any of the cord register relays, it will be obvious that the operation of line register relays will cease. Upon the operation of relay 629, a circuit is established extending from grounded battery, through the winding and contact of relay 629, the winding of slow release relay 511, and the right hand contact of relay 509 to ground. Relay 511 is operated in this circuit, and in opening its normal contact, removes ground from the winding of relay 303. It will be recalled that this ground, through the normal contact of relay 511, short-circuited relays 305 and 309, while relay 303 was operated. Upon the removal of this ground, relays 305 and 309 operate in parallel from ground at the contact of relay 301, through the inner contact and winding of relay 303 to grounded battery. Relay 303 therefore remains energized, and the operation of relay 305 connects the tip and ring conductors of the cord circuit A to the toll line L. The operation of relay 305 also removes the ground connection from its normal contact, through resistance 306, whereupon relay 202, which was energized through this resistance, is released. The release of relay 202 opens the original energizing circuit for relay 205, but this relay is now locked through its inner right hand contact to ground at the contact of relay 201. 100

At the time the wipers of switch B were stepped to position 17, a circuit was established for relay 215, extending from grounded battery, through the winding of relay 215, and wiper 219 in position 17 to 105 115 120 125 130

ground. Relay 215 energizes in this circuit, and in so doing establishes a self-interrupting circuit for the stepping magnet 218, extending from grounded battery, through the winding and contact of said magnet, the left hand alternate contact of relay 215, and wiper 219 to ground. Magnet 218 operates and releases to step the wipers of switch B over the succeeding terminals thereof until said wipers have reached their normal positions where ground is no longer found upon the terminal engaged by wiper 219. Magnet 218 will then cease to operate, and the wipers of the switch will be brought to rest. The movement of wiper 220 to position 17 closes an obvious energizing circuit for relay 113 of the cord register, and this relay in operating disconnects ground from its normal contact, to open the locking and holding circuits of the transfer and register relays of the cord register, whereupon all of these relays are restored to normal, and the register is then in condition for another operation.

The energization of relay 215 also establishes a circuit for relay 206 extending from grounded battery through the winding and continuity contacts of relay 206, the inner left hand contact of relay 205, and the inner right hand contact of relay 215 to ground. Relay 206 energizes and locks through its left hand alternate contact, the outer right hand contact of relay 205, and the contact of relay 201 to ground. In opening its left hand normal contact, relay 206 causes the release of relay 207 to connect the cord circuit A through normal contacts of relay 207 and alternate contact of relay 204 to the toll line L. The opening of the inner right hand contact of relay 206 breaks the holding circuit through the windings of relays 212 and 214, and these relays thereupon restore to normal. Relay 200 also releases, and lamp 211 is extinguished due to the release of transfer relay 111 and energization of relay 206. Relays 201, 204, 205 and 206 of the apparatus individual to cord circuit A are now operated and remain in this condition throughout the duration of the call.

The operation of relay 305, as previously described, closes an obvious energizing circuit for relay 310. This relay, in operating, establishes an energizing circuit for relay 311 extending from grounded battery, through the normal contact of differential relay 312, winding of relay 311 and from thence to ground at the alternate contact of relay 310. The energization of relay 311 disconnects the left-hand winding of differential relay 320 from the conductor 322, to prevent the operation of said relay while relay 311 is operated. Relay 310 also closes a circuit extending from ground through the alternate contact thereof, the right-hand

normal contacts of relays 313 and 314, the winding of relay 315, the contact of relay 316 and the left-hand normal contact of relay 317 to grounded battery. Relay 315 energizes in this circuit and temporarily locks through its inner left-hand contact. The energization of relay 315 establishes an obvious energizing circuit for relay 318 and this relay then locks through its left-hand contact to ground at the inner left-hand normal contact of relay 314. By the closure of the inner right-hand contact of relay 315, ground is extended from thence through the outer left-hand contact of relay 314, the outer right-hand contact of relay 319, to a terminal individual to toll line L in the bank of switch F over which the wiper 416 passes.

The switch F is common to all the toll lines in the group in which the toll line L is located and is designed to connect the apparatus of Fig. 3 and of the line register to that associated with the sending distributor SD. This sending distributor is preferably of a type similar to distributors employed in printing telegraphy and is operated in synchronism with a receiving distributor RD, (Fig. 8) located at a distant office whereby impulses from the outgoing office may be transmitted to the distant office to indicate at the latter office the particular toll line which has been taken for use. In accordance with the present invention, the distributors are also employed for transmitting the code set up on the line register to the distant office to operate the call indicator located at said distant office before the incoming operator.

Association of signaling apparatus with selected toll line.

Referring again to the operation of relay 315, the closure of the outer right-hand contact of this relay establishes a circuit from ground through said contact, the inner right-hand contact of relay 319 and the winding of relay 415 to grounded battery. Relay 415 operates and in so doing, establishes a self-interrupting circuit for the stepping magnet 417 of the switch F extending from grounded battery through the winding and contact of said magnet, the normal contact of relay 418 and the contacts of relays 419 and 415 to ground. Magnet 417 operates to step the wipers 416 and 420 to 426 of the switch to seek associated terminals individual to the toll line L. This operation continues as long as the wiper 416 does not encounter ground upon an associated terminal, but as soon as wiper 416 engages the terminal to which ground is connected by the energization of relay 315, a circuit is established for relay 418 from grounded battery, through the left-hand winding of relay 418, and the wiper 416 to

ground on said terminal. The energization of relay 418 opens the stepping circuit for magnet 417, whereupon the wipers of switch F come to rest upon the terminals individual to line L. With the wipers of the switch F engaging terminals individual to line L, the apparatus is in condition to transmit a code of impulses through the distributor SD to the receiving distributor RD over a common conductor P terminating in windings of polar relays 428 and 828. This code, in the present arrangement, consists of five impulses which are successively transmitted and which differ with respect to their polarities. Each toll line has a different combination of positive and negative polarities to distinguish the same, line L being represented by a code consisting of two positive impulses, a negative impulse, a positive impulse and then a negative impulse. The first four of these potentials are connected to the normal contacts of the transfer relays 429 to 432 which operate in a manner to appear in the course of the description, after the toll line code has been transmitted, to connect the line register with the sending distributor whereby the impulses from said line register are passed over the common signaling path P to operate the proper lamps in the call indicator of Fig. 10.

Upon the operation of relay 418, as previously described, a circuit is established for the start magnet 433 of the sending distributor, said circuit extending from grounded battery, through the lamp 434, ring 435 of the sending distributor, brush arm 436, start segment 437, the outer right-hand contact of relay 418 and the winding of magnet 433 to ground. The magnet 433 is energized and the lamp 434 lighted in this circuit. The lighting of the lamp 434 indicates that the distributor is in use. The energization of magnet 433 releases the brush arm 436 of the sending distributor which thereupon makes a complete revolution. As soon as the brush arm 436 passes beyond the start segment 437, the energizing circuit for the start magnet 433 is opened and the armature of said magnet is thereby moved to a position in the path of rotation of the brush arm 436 so that this arm engages and is stopped by said armature upon completing its revolution.

Upon engagement of the brush arm 436 with the segment 438 at the beginning of its revolution, a circuit is established from positive pole of battery through the segment 438, brush arm 436, ring 439 and from thence over one path through the lower winding of polar relay 428 and the artificial line to ground and over another path through the upper winding of relay 428, common conductor P, both windings of polar relay 828 and the artificial line to ground. The closure of this circuit has no effect upon the polar relay 428, but causes relay 828 to close its upper contact. A circuit is thereby closed from grounded battery through the upper contact of relay 828, the segment 800 of the receiving distributor RD, brush arm 801 thereof, segment 802 and the winding of start magnet 803 to ground. The magnet 803 operates to release brush arm 801 so that the same will make a complete revolution in synchronism with the sending distributor SD. During the rotation of brush arms 436 and 801, the impulses are transmitted over the common conductor P in accordance with the code designation of toll line L. In order that the transmitted code combinations may be translated into suitable signals for appropriate toll lines, the invention preferably includes the provision of receiving apparatus associated with the receiving distributor RD which is selectively responsive to the transmitted code combinations to cause the operation of signals individual to the various toll lines. The selective receiving apparatus, as herein shown, includes a plurality of locking relays 804 to 809, the locking circuits of which are controlled by a common relay 810. The apparatus further includes a pyramid relay combination of a type well known in the signaling art, the relays of this combination being indicated by the numerals 811 to 825. In accordance with the code signaling impulses transmitted, the apparatus including the locking and pyramid relays responds to provide a path through contacts of said relays over which the signal individual to the toll line selected is operated.

Returning now to the operation of sending distributor SD, when the brush arm 436 passes from the start segment 437 to release the start magnet 433 and then engages the segment 440, a circuit is established from grounded battery through the lamp 434, the ring 435, brush arm 436, segment 440 and the winding of relay 441 to ground. Relay 441 operates and, in so doing, establishes an energizing circuit for relay 317 extending from grounded battery through the contact of relay 441, the wiper 420 and the terminal engaged thereby, the normal contact of relay 321 and the winding of relay 317 to ground. In energizing, relay 317 disconnects battery through its outer normal contact from the locking circuit of relay 315 and this relay thereupon releases. The operation of relay 317 establishes an energizing circuit for slow-release relay 313 extending from grounded battery, through the alternate contact of relay 317, right-hand alternate contact of relay 318, which is locked at this time, the winding of relay 313 and the inner left-hand normal contact of relay 314 to ground. Relay 313 energizes

and locks through its inner left-hand alternate contact and winding to ground at the last-mentioned contact of relay 314. The deenergization of relay 315 removes ground 5 from the winding of relay 415 which then releases and also removes ground from the terminal engaged by wiper 416 to open the energizing circuit of relay 418. The latter relay, however, is maintained energized 10 through a locking circuit extending from ground through the right-hand winding of said relay, the contact of relay 442 and the inner right-hand contact of relay 418 to grounded battery. The release of relay 415 15 permanently opens the stepping circuit of magnet 417 so that upon release of relay 418, at the termination of the rotation of the distributor SD, the circuit for said stepping magnet will not be closed and the 20 wipers of switch F will, therefore, be maintained in their positions in contact with terminals individual to the toll line.

As soon as the brush arm 801 of the receiving distributor engages segment 826 at 25 the beginning of rotation of said arm, a circuit is established from grounded battery through the ring 827, brush arm 801, segment 826 and winding of relay 810 to ground. This relay energizes and remains 30 in this condition as long as brush arm 801 is in engagement with the segment 826. In energizing, relay 810 connects ground to its contact to prepare a locking circuit for such relays 804 to 809 as are energized by the 35 transmission of the code signals over the common signaling path.

At the same time that the circuit is established for relay 441, brush arm 436 engages the sending segment 443 to establish a circuit 40 extending from positive pole of battery through the normal contact of relay 429, wiper 421, segment 443, brush arm 436, ring 439 and from thence over the previously described path through windings of 45 polar relays 428 and 828 to ground. The polar relay 828 again closes its upper contact. When this impulse is transmitted, brush arm 801 is in engagement with the segments 829 and 830. Inasmuch as the 50 lower contact of polar relay 828 is opened at this time, the battery at the polar relay will not be connected to segment 829 and therefore, a circuit will not be established for the first locking relay 804. The second 55 impulse of the code combination is transmitted when brush arm 436 engages segment 444 and brush arm 801 engages segment 831. The circuit for this impulse extends from positive pole of battery through 60 the normal contact of relay 430, wiper 422, segment 444, the brush arm 436, segment 439 and then over the conductor P through the windings of polar relays 428 and 828. 65 This positive impulse again causes the polar relay 828 to close its upper contact.

This disconnects battery from the lower contact of the polar relay and hence relay 805 will not be operated through segments 829 and 831 and the brush arm 801. The third impulse to be transmitted is of negative polarity which is connected to the normal contact of relay 431, and then to wiper 423 and upon engagement of brush arm 436 with segment 445 and brush arm 801 with the segment 832, this impulse will be transmitted over an obvious path to cause relay 828 to close its lower contact. A circuit is thereupon established extending from grounded battery through the lower contact of relay 828, segment 829, brush arm 801, segment 832 and the right-hand winding of relay 806 to ground. Relay 806 energizes and locks through its left-hand winding and contact to ground at the contact of relay 810. Brush arm 436 then successively 75 engages segments 446 and 447 to transmit the remaining two impulses of the code combination. These impulses are received at the time the receiving distributor brush arm is in engagement with segments 833 80 and 834, respectively. The fourth impulse transmitted being of positive polarity, it will be obvious from an understanding of the previous description, that relay 807 will not be energized. The fifth impulse of negative polarity causes the operation of relay 808 which then locks through its left-hand winding and contact to ground at the contact of relay 810. Thus in the transmission 85 of the code impulses for the toll line L, relays 806 and 808 have been caused to operate and lock. When the brush arm 436 engages segment 448, an impulse of positive polarity will be transmitted over the path P 90 from the normal contact of relay 449. This positive impulse causes the closure of the upper contact of polar relay 828 and hence no circuit will be established for relay 809 through the segment 835. The battery of 95 negative polarity connected to the segment 450 which is engaged by brush arm 436 sends an impulse over the path P to cause the polar relay 828 to close its lower contact. At this time, brush arm 801 has passed from 100 segments 829 and 835 and hence the closure of the lower contact of relay 828 has no effect upon the receiving apparatus. At the same time the brush arm 436 engages the segment 450 it also makes contact with the segment 451 to establish an obvious energizing circuit for relay 442 which, in opening its contact, breaks the locking circuit for relay 418, which thereupon releases. Before the circuit for relay 442 is established, 105 the relay 441 is released by the brush arm passing from engagement with the segment 440 and relay 441 releases. The removal of battery from the contact of this relay causes the release of relay 317 to open the 110 original energizing circuit for relay 313, but 115 120 125 130

the latter relay remains in its locked condition. The return to normal of the brush arm 436 opens the circuit for lamp 434 which is extinguished to indicate that the distributor has completed its revolution.

The effect of the operation of relays 806 and 808 will now be described. Upon the energization of the relay 806, a circuit is established for pyramid relays 812 and 813 extending from grounded battery through the windings of said relays in series, the upper normal contact of relay 836 and the right-hand contact of relay 806 to ground. When brush arm 801 engages segments 837 and 838, relay 808 has already been energized and a circuit will therefore be established extending from the negative pole of 120 volt battery through the normal contact of relay 809, contact of relay 839, the segment of 837, brush arm 801, segment 838, right-hand alternate contact of relay 808, the left-hand normal contact of relay 811, the left-hand alternate contact of relay 812, the right-hand normal contacts of relays 814 and 819, the start conductor 700, the normal contact of relay 701 and the left-hand winding of the differential relay 702 to ground. The effect of the closure of this circuit will presently be described. When brush arm 801 moved from its normal position, the circuit of start magnet 803 was opened and this magnet released to return its armature into the path of the brush arm 801 so that the rotation thereof will be stopped after the same has passed from segments 837 and 838, to segments 800 and 802. The disengagement of brush arm 801 from the segment 826 opens the holding circuit for relay 810 which thereupon restores to open the locking circuits of relays 806 and 808 which thereupon release. The release of relay 808 causes the release of relays 812 and 813. However, before relays 806 and 808 release, the impulse of negative polarity transmitted from the 120 volt battery, as previously described, has become effective to energize the differential relay 702 which thereupon locks through its right-hand alternate contact to ground. This impulse is also transmitted through the right-hand winding of the differential relay 703 which relay responds to this impulse but does not lock inasmuch as the slow-release relay 704 is, at this time, in its normal condition. At the termination of the momentary impulse over conductor 700, relay 703 will therefore release and a circuit is established for relay 704 extending from grounded battery through the winding of said relay, the normal contact of relay 703 and the right-hand alternate contact of relay 702 to ground. The operation of relay 704 has no material effect at this time. When relay 703 energized, a circuit was established for the slow-operate and release relay 705 extending

through the right-hand alternate contact of relay 703 to ground at the right-hand alternate contact of relay 702. However, due to its slow to operate nature, relay 705 will not close its alternate contacts during the energization of relay 703. The closure of the right-hand alternate contact of relay 702 establishes a circuit for guard lamp 706 individual to the toll line L at the incoming office to light this lamp whereby the incoming operator is informed that a call is being extended over this line. The circuit for lamp 706 extends from grounded battery through the lamp, the lower normal contact of relay 707, and from thence to ground at the right-hand alternate contact of relay 702.

Incoming operator responds to the call over toll line L.

The incoming operator, upon observing the lighted condition of the guard lamp 706, responds to the call by first operating the assignment key 708 which establishes a circuit extending ground through the right-hand alternate contact of relay 702, the lower normal contact of relay 707, the contacts of key 708 and from thence in parallel through the windings of relay 701 and 709 to grounded battery, the latter relay finding battery at the normal contact of relay 710. Relays 701 and 709 operate and the former relay locks through its inner right-hand alternate contact, and the lower normal contact of relay 707 to ground at the right-hand alternate contact of relay 702. The operation of relay 701 disconnects signaling conductor 700 from the left-hand winding of relay 702 and connects the same through its left-hand alternate contact to the left-hand winding of relay 900 to operate this relay when the transmission of the code impulses from the line register (Fig. 6) is initiated, as will appear in the course of the description. The operation of relay 701 also closes a circuit extending from grounded battery through the assignment lamp 711, the outer right-hand contact of relay 701 and from thence to ground over the locking circuit of the latter relay. The lighting of the lamp 711, which is individual to the toll line L, provides an indication to the incoming operator as to which toll line has been taken so that while she is awaiting the operation of the call indicator (Fig. 10) to indicate the number of the wanted line, she may attend to the supervision of other lines under her control.

When relay 709 operates, a circuit is established from ground through the inner left-hand alternate contact of this relay, the outer right-hand normal contact of relay 712, the left-hand normal contact of relay 713 and the continuity contacts and winding of the slow-operate-and-release relay 714 to

grounded battery. This relay energizes and locks through its right-hand alternate contact, the normal contact of slow-release relay 715, the outer right-hand normal contact of relay 712 and the inner alternate contact of relay 709 to ground. Inasmuch as relay 714 is slow to operate, a circuit will be established, before relay 714 has opened its continuity contacts, extending from ground over the energizing path of relay 714 through the left-hand normal contact of relay 713 and from thence through the left-hand continuity contacts of relay 714, the continuity contacts and winding of relay 716, the inner right-hand normal contact of relay 713 and the winding of relay 840 to grounded battery. The relay 840 is associated with a mechanism SD' similar in all respects to the mechanism shown in Fig. 4 and including the switch F and the sending distributor SD. In the circuit described for relays 716 and 840, these relays energize and relay 716 locks from ground through its right-hand alternate contact and winding and from thence over the energizing circuit for said relay. The operation of relay 716 establishes a circuit extending from ground through the inner left-hand alternate contact of relay 716, the normal contact of slow-to-release relay 717 and the winding of relay 718 to grounded battery. Relay 718 energizes to establish a circuit extending from grounded battery through the winding and contact of relay 718, the winding of relay 717, the inner right-hand normal contact of relay 712 and the right-hand alternate contact of relay 702 to ground. However, relay 717 does not energize at this time, due to its being short-circuited by the ground connected to the inner left-hand contact of relay 716. The energization of relay 716 also connects ground to the individual signaling conductor 719 through the outer left-hand contact of said relay and this ground is extended to a terminal individual to toll line L and included in a switch similar to switch F in the mechanism SD'. The operation of relay 840 connects ground through its contact to cause the energization of a relay in the mechanism SD' similar to relay 415 and the energization of this latter relay causes the rotary switch to step in the same manner as previously described for switch F until the ground from the outer left-hand contact of relay 716 is encountered, whereupon the rotary switch stops upon the terminals individual to the toll line. The sending distributor of the mechanism SD' is now operated in the same manner as described in connection with distributor SD to send the code of impulses individual to toll line L to the outward office where it is received at the mechanism RD' which includes apparatus similar to that associated with the receiving distributor RD. Transmission of this code of impulses to the outward office results in the release of the line register of Figs. 5 and 6, whereby the codes established by the relays thereof are transmitted to the call indicator before the incoming operator to light the proper lamps at said indicator in a manner which will presently be described in detail.

During the rotation of the sending distributor of mechanism SD', the relay in said mechanism similar to relay 441 is operated to connect battery to conductor 843 to effect the energization of relay 713. When this relay operates the locking circuit of relay 716 is opened and the latter relay deenergizes. The restoration of relay 716 removes the short circuit for relay 717 which thereupon operates over the circuit previously described therefor through the winding and contact of relay 718. The operation of relay 717 has no effect at this time.

As the code of impulses individual to line L is received by the mechanism RD', the conductor 322, individual to the toll line and similar to conductor 700, is selected by the mechanism RD' in the same manner as described in connection with the mechanism RD. Upon the selection of this conductor 322, 120 volt negative battery is momentarily connected thereto and extended thereover through the left-hand winding of the differential relay 312 to ground. Relay 312 is operated by this impulse of current and locks from battery through its alternate contact and right-hand winding to ground at the contact of relay 310. The impulse of current will not energize differential relay 320 due to the operated condition of slow-release relay 311 at this time. The energization of relay 312 establishes a circuit for relay 321 extending from grounded battery through the winding of relay 321, the right-hand normal contact of relay 323, the left-hand contact of relay 312 and the left-hand normal contact of relay 320 to ground. Relay 321 energizes to transfer the conductor extending from the terminal engaged by brush 420 of switch F from the winding of relay 317 to the winding of relay 324 through the innermost normal contact of relay 326. The energization of relay 312 also establishes an energizing circuit for relay 325 extending from grounded battery through the right-hand alternate contact of relay 312, the left-hand normal contact of relay 323, the winding of relay 325 and from thence to ground at the alternate contact of relay 310. The energization of relay 325 closes circuits for relays 323 and 328 extending through the inner left-hand contact of relay 325 and from thence in series with the operating circuit of relay 325. However, relays 323 and 328 are short circuited at this time by the battery connected to the right-hand contact of relay 312, the left-

hand normal contact of relay 323, and the inner left-hand contact of relay 325. The operation of relay 325 again causes the energization of relay 315 over a circuit extending from grounded battery through the left-hand normal contact of relay 317, the contact of relay 316, the winding of relay 315, the outer normal contact of relay 326, the right-hand contact of relay 325 and the alternate contact of relay 310 to ground. Relay 315 operates and locks and in so doing again causes the energization of relay 415 and 418, as previously described. The sending distributor SD then operates to transmit the same code of impulses to the receiving distributor RD, as was previously transmitted. In response to this series of impulses relays 806 and 808 again operate and lock which results in the energization of relays 812 and 813 to again select the impulse receiving conductor 700. It will be recalled that the first impulse transmitted over conductor 700 resulted in the energization of relay 702 which was followed by the energization of relay 701 to transfer the conductor 700 from the left-hand normal contact of relay 701 to the front contact thereof and to the left-hand winding of the relay 900. Therefore, when this second impulse is transmitted to the conductor 700, relay 900 operates and locks from ground through its right-hand winding and contact to battery which is connected to the lower normal contact of the transfer relay 912. When relay 900 is energized the battery connected to the right-hand contact thereof is extended to ground through the winding of relay 839 which thereupon energizes and remains in this condition until the various codes of impulses have been transmitted to the call indicator to light the lamps thereof. While the sending distributor SD is transmitting the code of impulses which results in the energization of relay 900, relay 441 again operates to establish a circuit for relay 324 extending from grounded battery through the contact of relay 441, the wiper 420 and terminal engaged thereby, the alternate contact of relay 321, the inner normal contact of relay 326, the winding of relay 324 and from thence over the energizing circuit for relay 321 to ground at the left-hand normal contact of relay 320. The energization of relay 324 in this circuit prepares an energizing circuit through its left-hand contact and winding for relay 326 but the latter relay is short-circuited through its inner normal contact and the alternate contact of relay 321 during the energization of relay 441. The energization of relay 324 furthermore establishes a circuit extending from grounded battery through the right-hand contact of relay 324, the middle normal contact of relay 326, the inner left-hand alternate contact of relay 309, wipers 406 and 508, winding of relay 512 and from thence in series through the middle alternate contacts of transfer relays 600, 604, 608, 612, 616, 620, 624 and 628 to ground. Relay 512 energizes in this circuit and thereby connects ground to its contact and extends the same through the upper alternate contacts of transfer relays just mentioned and through the winding of stepping magnet 513 of rotary switch G to grounded battery. The magnet 513 is energized but the mechanism controlled thereby is so arranged that the wipers 514, 515, 516, 517 and 518 of switch G are stepped only upon the release of said magnet. After the code of impulses for line L has been transmitted to the receiving distributor RD and the brush arm 436 of distributor SD has passed from engagement with segment 440, relay 441 releases. The brush arm 436 continues to its normal position to prepare the circuit for the transmission of code impulses which become effective to operate the call indicator. The release of relay 441 removes the short circuit from relay 326 which thereupon energizes through its winding, left-hand alternate contact and winding of relay 324 and from thence over the energizing circuit of the latter relay. The energization of relay 326 disconnects battery at relay 324 from the winding of relay 512 which thereupon releases to cause stepping magnet 513 to step the wipers 514 to 518 to position 2. The release of relay 441 also permits the energization of relays 429 to 432 in series with the left-hand contact and winding of relay 324. The operation of relays 429 to 432 disconnects the potentials forming the code individual to line L from the normal contacts of such relays and connects the transmitting segments 443, 444, 445 and 446 of the sending distributor SD to conductors 452, 453, 454 and 455, respectively. When relay 326 energizes a circuit is established from grounded battery through the outer left-hand contact of relay 325, resistance 327, the outer alternate contact of relay 326, the contact of relay 328, wiper 426 of switch F and the windings of relays 456 and 419 to ground. Relay 456 is marginal and will not operate due to the inclusion of resistance 327 in this circuit, but relay 419 responds to the closure of this circuit to prevent any further operation of stepping magnet 417 so that the wipers of switch F will remain upon the terminals individual to line L. However, when switch G steps to position 2, battery is extended through the wipers 518, 503 and 401, the winding of relay 316 and from thence over the circuit through the contact of relay 328, wiper 426

and the windings of relays 456 and 419. Resistance 327 being excluded from this circuit, relay 456 energizes. The operation of this relay establishes an energizing circuit for 6 start magnet 433 extending from ground through the winding of said magnet, contact of relay 456, segment 437, brush arm 436 and segment 435 to grounded battery through the lamp 434. The operation of the start 10 magnet releases the brush arm 436 to permit the same to make one revolution whereby the first of a series of eight sets of impulses are transmitted to the receiving distributor RD, these eight sets including the 15 three office, four number and one station designations. The circuit through relay 316 in series with the windings of relays 456 and 419 causes the energization of relay 316 to open the locking circuit for relay 315 which 20 releases to remove ground from the terminal engaged by brush 416 and from the winding of relay 415, which relay thereupon restores.

The apparatus is now in condition to 25 transmit the eight sets of impulses comprising the code of the line which is being called and these impulses are transmitted in accordance with the condition of the register relays in Fig. 6. With the wipers of 30 switch G in position 2 the register relays 602, 603, 606 and 607 are associated with the sending distributor SD. It will be recalled that of the register relays mentioned, only relays 606 and 607 are energized. 35 Therefore, the code for the first series of the eight comprises two positive and three negative impulses transmitted in the order named. The two positive polarities are connected through the normal contacts of relays 602 and 603, the next two negative impulses through the right-hand alternate contacts of relays 606 and 607 and the fifth or negative impulse through the wiper 425 of switch F. The first positive impulse is 40 transmitted when brush arm 436 engages segment 443, at which time an impulse of positive polarity has already been transmitted, by the engagement of segment 438, to operate the start magnet 803 of the receiving distributor RD, as previously described. When segment 443 is engaged the brush arm 801 is in contact with segments 826 and 830. The circuit for the first positive impulse extends from the source of 45 positive polarity through the normal contact of relay 603, wiper 514 in position 2, the alternate contact of relay 511, which is energized at this time as previously described, wiper 507, the left-hand contact of relay 412, wiper 405, the right-hand alternate contact of relay 309, conductor 452, the alternate contact of relay 429, wiper 421, segment 443, the brush arm 436, segment 439, the upper winding of polar relay 428, 50 conductor P and the windings of polar re-

lay 828 to ground. This positive impulse causes polar relay 828 to close its upper contact and hence no circuit will be established for locking relay 804. Brush arm 436 next engages segment 444 and brush arm 801 70 simultaneously engages segments 826 and 831. Shortly after the beginning of rotation of brush arm 801 the previously described energizing circuit for relay 810 is established and in closing its contact this 75 relay causes the energization of relays 836 and 841 over a circuit traceable from ground through the contact of relay 810, the left-hand contact of relay 900, the normal contact of relay 842, the windings of relays 836 and 841 in series, the right-hand contact of relay 900 and the lower normal contact of relay 912 to grounded battery. Relays 836 and 841 energize to disconnect the conductors associated with the right-hand front contacts of relays 804 to 807 from the group of pyramid relays and connects said conductors to normal contacts of transfer relays 901, 902 and 903. The energization of relay 836 prepares a circuit for relay 842 80 extending from grounded battery connected to the right-hand contact of relay 900 through the windings of relays 841 and 836, the lower alternate contact of the latter relay, winding of relay 842 and the contact of relay 913 to ground. However, during the energization of relay 810, which occurs at the beginning of the revolution of arm 801, relay 842 is short-circuited by ground 85 extending from the contact of relay 810 through the left-hand contact of relay 900, the normal contact of relay 842, and the lower alternate contact of relay 836. This short-circuit is maintained until the first 90 series of impulses has been transmitted and the receiving distributor has returned to its normal position. The second positive impulse is transmitted from the source through the normal contact of relay 602, the wiper 515 in position 2, the lower alternate contacts of relays 628, 624, 620, 616, 612, 608, 604 and 600, wipers 506 and 404, the outer left-hand alternate contact of relay 309, conductor 453, the alternate contact of relay 430, wiper 422, segment 444 and from thence 95 through windings of polar relays 428 and 828 over the common conducting path P. This positive impulse again causes polar relay 828 to close its upper contact with the result that no circuit is established for locking relay 805.

The next impulse of the series is of negative polarity and the circuit therefor extends from the source of current through the right-hand alternate contact of relay 607, wiper 516 in position 2, wipers 505 and 403, conductor 454, the alternate contact of relay 431, wiper 423, segment 445, brush arm 436, segment 439, thence over the common signaling path and through windings 100 105 110 115 120 125 130

of polar relays 428 and 828 to ground. This impulse being of negative polarity causes relay 828 to close its lower contact and establish the previously described circuit for locking relay 806 through segments 829 and 832 of the receiving distributor RD. Relay 806 energizes and locks to ground at the contact of relay 810. The next impulse is also of negative polarity and the circuit therefor extends from the right-hand alternate contact of relay 606, wiper 517 in position 2, wipers 504 and 402, conductor 455, the alternate contact of relay 432, wiper 424, segment 446, brush arm 436, segment 439 and from thence over the common signaling path P. Relay 828 again closes its lower contact to establish the circuit for locking relay 807 through segments 829 and 833 of the distributor RD. Relay 807 energizes and locks to ground at the contact of relay 810. The fifth and last impulse of this series is again of negative polarity and extends from a source of current through wiper 425 and from thence over the previously described circuit through the windings of polar relay 828. The transmission of this impulse results in the energization and locking of relay 808, but the operation of this relay at this time has no useful function.

At the beginning of the first revolution of the brush arm of the sending distributor SD, relay 441 is energized as previously described. Relay 326 being now energized as a result of the transmission of the code of impulses individual to toll line L which caused the operation of relay 900, the energization of relay 441 during the first revolution of brush arm 436 to transmit the first series of impulses from the line register closes a circuit extending from grounded battery through the contact of relay 441, wiper 420, the alternate contact of relay 321, the inner left-hand alternate contact of relay 309, the wipers 406 and 508, the winding of relay 512 and from thence to ground over the previously described energizing circuit for relay 512 through the middle alternate contacts of relays similar to relay 600. Relay 512 energizes in this circuit to establish the previously described stepping circuit for magnet 513 which thereupon energizes but does not step the wipers controlled thereby from position 2 until said magnet is released. Upon disengaging the segment 440, after the five impulses of the first series have been transmitted, brush arm 436 opens the energizing circuit for relay 441 which thereupon releases to open the energizing circuit for relay 512, which, in restoring, breaks the stepping circuit for magnet 513. The release of this magnet causes the wipers of switch G to step to position 3. Inasmuch as battery is connected to all of the off normal contacts engaged by wiper 518 of switch G, it will be obvious that the circuit for marginal relay 456 will be maintained and that, therefore, the energizing circuit for start magnet 433 will be continuously closed.

After locking relays 806, 807 and 808 have been energized and locked, brush arm 801 engages segments 837 and 838, but no effect upon the system is produced thereby due to the energization of relay 839. The brush arm 801 next disengages segment 826 to open the energizing circuit for relay 810 which thereupon restores to open the locking circuits for relays 806, 807 and 808. Before this occurs, however, the energization of relay 806 establishes a circuit extending from ground through the right-hand contact of said relay, the upper alternate contact of relay 836, the upper normal contact of relay 902 and the lower winding of call indicator relay 1000 to grounded battery. This relay energizes and locks through its upper winding and middle alternate contact to ground at the contact of relay 913. The relay 1000 together with other similar relays 1001, 1002 and 1003 are individual to the lamps of the call indicator which are employed to designate the first letter of the office code. Similarly, relays 1004, 1005, 1006 and 1007 are assigned to the lamps designating the second letter of the office code; relays 1008, 1009, 1010 and 1011 to lamps which indicate the third letter of the office code; and relays 1012, 1013, 1014 and 1015 to the lamps which indicate the letters of station designations. The relays and circuits therefore which are assigned to the numerical lamps have been omitted from the showing for purposes of economy but it is to be understood that these relays and circuits are similar in every respect to those of the office designations. To illustrate the manner in which circuits for these numerical lamps are established, two lamps 1016 and 1017 representing digits 1 and 0 have been shown in each of the office groups of lamps.

Returning now to the point in the operation where relay 1000 was energized, it will be seen that relay 1001 will also be energized due to the operation of relay 807, the circuit for relay 1001 extending from grounded battery through the lower winding of said relay, the lower normal contact of relay 902, the middle alternate contact of relay 836 and the right-hand contact of relay 807 to ground. After energizing relay 1001 locks through its upper winding and middle alternate contact to ground at the contact of relay 913. Relays 1000 and 1001 remain locked throughout the transmission of the seven remaining series of impulses from the line register so that when all of these series have been received at the call indicator, cir-

cuits will be established, as will appear in the course of the description, for the various lamps which will be lighted to indicate the office, numerical and station designations of 5 the wanted line.

When relay 810 releases at the termination of the first revolution of the brush arm of distributor RD, the short circuit previously described for relay 842 is removed 10 and this relay will then energize in series with relays 836 and 841. The brush arm 801 of the receiving distributor RD now comes to rest in its normal position, as previously described.

15 The apparatus is now ready for the second series of impulses from the line register and inasmuch as the start magnet 433 of the distributor SD is maintained energized during the transmission of these series, it 20 will be obvious that the said distributor will continue in its rotation. Upon engaging segment 438 the brush arm 436 causes the energization of start magnet 803 of the receiving distributor RD, as previously described, to release the brush arm of this distributor so that the same will operate in synchronism with the brush arm 436. At the start of the rotation of the brush arm of distributor SD, relay 441 is again energized 25 to cause the operation of relay 512 which in turn energizes magnet 513 to prepare for stepping the brushes of switch G from position 3 to position 4, which operation occurs, as will be understood from the 30 previous description, when relay 441 releases at the termination of the transmission of the series of impulses for the second office designation.

The code for the second series of impulses 40 is determined by the condition of relays 611, 610, 615 and 614 in the order named. It will be recalled that of these relays only relay 610 is energized. Therefore, the code for the second series will consist of positive 45 then negative followed by two positive and finally a negative impulse, the last named impulse being controlled by wiper 425, as previously described. This series of impulses upon being transmitted to receiving 50 distributor RD through the wipers 514 to 517 of switch G in position 3, through circuits which are now believed to be obvious, causes the operation of relays 805 and 808, the energization of the latter having no 55 effect. When relay 810 is energized at the beginning of the rotation of the brush arm of the receiving distributor, a circuit is established from ground through the contact of relay 810, the left-hand contact of 60 relay 900, the alternate contact of relay 842, the normal contact of relay 903 and the winding of relays 902 and 901 in series to grounded battery. Relays 901 and 902 65 energize and the closure of the lower alternate contact of the latter relay establishes

an energizing circuit for relay 903, but this relay does not energize at this time due to the short-circuit produced by the energization of relay 810 in the same manner as described in connection with relay 842. Upon 70 the operation of relay 805 a circuit is established from ground through the right-hand contact of this relay, the lower alternate contacts of relays 841 and 901 in series, the lower normal contact of relay 904 and the lower winding of relay 1006 to grounded battery. Relay 1006 energizes and locks through its upper winding and middle alternate contact to ground at the contact of relay 913. After the series of impulses 80 has been transmitted, relay 810 releases to release relays 805 and 808 and to remove the short circuit from relay 903 which thereupon energizes in series with relays 901 and 902. Upon the release of relay 441 85 at the termination of the revolution of brush arm 436, relay 512 and magnet 513 release and the wipers of switch G are stepped to position 4.

The series of impulses for the third office 90 designation is now transmitted. Register relays 619, 618, 623 and 622 control the polarities for this series. Of these relays, only the relay 622 is energized. This relay controls the fourth impulse transmitted the 95 three preceding impulses being of positive polarity. The fourth and fifth impulses are of negative polarity. The distributors SD and RD operate as previously described and the reception of this series of impulses 100 at the distributor RD causes the energization of relays 807 and 808, the operation of the latter again having no effect. At the beginning of the rotation of brush arm 801 relay 810 is again energized to cause the 105 energization of relays 904 and 905 in a circuit extending from grounded battery through these relays in series, normal contact of relay 906, the alternate contacts of relays 903 and 842, the left-hand contact 110 of relay 900 and the contact of relay 810 to ground. Relays 904 and 905 energize and the latter relay establishes an energizing circuit for relay 906 but the latter relay does not operate until the short 115 circuit therefor is removed by the release of relay 810. The energization of relay 807 closes the circuit extending from ground through the right-hand contact of this relay, the middle alternate contacts of relays 836, 902 and 905, the lower normal contact 120 of relay 908 and the lower winding of relay 1009 to grounded battery. Relay 1009 energizes and locks through its upper winding and middle alternate contact to ground at the contact of relay 913. Upon the release of relay 810 at the termination of the rotation of brush arm 801, relay 906 energizes. Upon the release of relay 441 at the termination 125 of the rotation of brush arm 436, 130

wipers of the switch G are stepped to position 5.

Four series of impulses corresponding to the numerical designations of the wanted line are now transmitted in the same manner as described in connection with the impulses of the office designations with the result that a certain relay or relays individual to each group of number lamps are operated. During the transmission of these series of impulses, transfer relays 907, 908 and 909 and other succeeding relays similar thereto are operated.

The last series of impulses corresponding to the station designation of the wanted line is now transmitted. This series of impulses is controlled by relays 627, 626, 631 and 630, of which relays 627 and 630 are energized. The code for this last series, therefore, consists of negative, positive, positive, negative and negative (from wiper 425) impulses in the order named. This code of impulses being received at the receiving distributor RD causes the operation of relays 804, 807 and 25 808. The operation of relay 804 establishes a circuit extending from ground through the right-hand contact of said relay, the upper alternate contacts of relays 841, 901, 904, 907 and 910 and the lower winding of relay 30 1015 to grounded battery. Relay 1015 energizes and locks through its upper winding and lower alternate contact to ground at the contact of relay 913. The operation of relay 807 closes a circuit from ground through 35 the right-hand contact of relay 807, the middle alternate contacts of relays 836, 902, 905, 908 and 911 and the lower winding of relay 1013 to grounded battery. Relay 1013 energizes and locks through the upper winding 40 and contact to ground at the contact of relay 913. After relays 1013 and 1015 have operated relay 810 is released to remove the short-circuit established thereby for relay 45 912 and the latter relay thereupon energizes in series with relays 910 and 911 which were energized when relay 810 operated at the beginning of the last revolution of brush arm 801. The results of the operation of relay 50 912 will presently be described. The eight series of impulses have now been transmitted with the result that relays 1000, 1001, 1006, 1009, 1013 and 1015 of the call indicator have been energized and locked up.

While the last series was being transmitted 55 the wipers of switch G were in position 9 and after the termination of this series of impulses and consequent release of relay 441, said wipers are stepped to their normal positions by the release of magnet 513. The removal of battery from wiper 518 when the same steps to normal position causes the release of relays 316 and 456, but relay 419 remains energized through the resistance 327 included in the previously described circuit 60 for relay 419. The release of relay 456 opens

the energizing circuit for start magnet 433 so that upon completing its last revolution the brush arm 436 is stopped in its normal position by the armature of said start magnet.

Upon the energization of relay 912 as previously described, a circuit is established extending from grounded battery through the alternate contact of relay 912, the left-hand alternate contact of relay 709, and the winding of relay 710 to ground. Relay 710 operates in this circuit to remove battery from the winding of relay 709 whereupon the latter relay releases. The restoration of relay 709 removes ground at its inner alternate contact from the locking circuit of relay 714 which thereupon releases. Relay 709 also closes a circuit extending from grounded battery through the winding of relay 840, the outer right-hand contact of relay 713, winding of slow-release relay 714, right-hand normal contact of relay 716, right-hand contacts of relays 717 and 709, the continuity contacts of slow-operating relay 720, normal contact of supervisory relay 721, and the right-hand contact of relay 702 to ground. Relay 712 energizes in this circuit to open the holding circuit for relays 717 and 718 whereupon these relays restore. Relay 712 locks through its right-hand alternate contact to ground at the similar contact of relay 702. Relay 840 also energizes in the circuit for relay 712, and the energization of relay 840 has the same effect as previously described, namely, to energize a relay in the sending mechanism SD' similar to the relay 415 which controls the stepping of the switch F. This switch in mechanism SD' is already connected to terminals of line L due to a previous operation. The energization of relay 712 also establishes a circuit extending from grounded battery through the left-hand winding of a relay in the mechanism SD' similar to relay 418 through a wiper of the switch F in said mechanism, conductor 719, left-hand contact of relay 712, conductor 721', and from thence to ground through the winding of a relay in the mechanism SD' similar to relay 457. The relay similar to relay 418 energizes to 105 establish an energizing circuit for the start magnet of the sending distributor of the mechanism SD' whereby a code of signals for line L is transmitted over the common signaling path P to the receiving mechanism RD' at the outward office. The relay similar to relay 457 at mechanism SD' energizes in the circuit described therefor, and thereby establishes a circuit for a relay similar to relay 449, extending from ground through the contact of the relay 457, winding of the relay 449, and the inner right-hand contact of relay 418 to grounded battery. Relay 449 at mechanism SD' energizes and locks 110 through its left-hand contact during the en- 125

- ergization of relay 418. By closing its right-hand alternate contact, relay 449 connects negative potential to the segment 448 of the sending distributor at the mechanism SD', so that when the brush at said mechanism engages this segment the negative potential connected thereto will cause the polar relay 428 to close its lower contact and thereby establish a circuit for the locking relay in the mechanism RD' similar to the relay 809. The operation of this relay 809 at mechanism RD' connects positive 120 volt battery to the right-hand alternate contact of relay 809 from whence this battery is extended to the signal receiving conductor 322 and through the left-hand winding of the relay 312 to ground. At this time, relay 311 is released and the momentary impulse through the conductor 322 will also be extended through the left-hand winding of the differential relay 320. This impulse being of positive polarity will cause relay 312 to release and will operate relay 320, but this relay immediately releases since the current flowing through the locking winding opposes that flowing through the left-hand winding. The momentary operation of relay 320 has no effect. At the termination of the transmission of the code of impulses from mechanism SD' to the receiving mechanism at the outward office, the latter mechanism restores to normal in a manner which will be understood from the foregoing description of the mechanism RD. During the rotation of the sending distributor at SD' the relay 441 thereof is operated to energize the relay 713 as previously described whereupon the energizing and locking circuit for relays 712 and 840 is opened and these relays thereupon release. Relay 712 is slow in releasing to allow ample time to obtain the results of the energization of relays in the mechanism SD' similar to relays 457 and 449 of the mechanism SD. When the left-hand contact of relay 712 is opened, relay 457 releases but relay 449 remains energized in its locking circuit controlled by the relay 418 of the mechanism SD' which relay is not released until the brush arm of the sending distributor at SD' engages its segment 451 to energize the relay corresponding to relay 452. The release of the differential relay 312 permits the relays 323 and 328, which were normally short-circuited by the battery connected to the right-hand alternate contact of relay 312, to operate in series with the inner left-hand contact and winding of relay 325. When relay 312 releases, the holding circuit for relays 321, 324, 326 and 429 to 432 extending through the left-hand contact of relay 312, is opened, and said relays thereupon restore to normal. The operation of relay 323 establishes a shunt path for relay 412 extending from ground through the left-hand alternate contact of relay 323, inner alternate contact of relay 304, wiper 400 and the alternate contact of relay 410. Due to this shunt, relay 412 is released and a substitute holding circuit is provided for relay 307 by the ground at the left-hand alternate contact of relay 323. The release of relay 412 removes ground from the winding of relay 410, which relay thereupon restores to normal. The closure of the normal contact of relay 410 establishes a stepping circuit for magnet 411, extending from grounded battery through the winding and contact of this magnet, the normal contact of relay 410, wiper 400 and from thence to ground at the left-hand alternate contact of the relay 323 through the inner alternate contact of relay 304. The operation of the stepping magnet 411 causes the wipers of switch C to step from the terminals individual to the toll line L. If the remaining lines of the group are idle, brush 400 will find ground at the normal contact of relay 304 whereupon the switch C will continue to step until its wipers have reached their normal positions, at which time wiper 400 no longer finds ground. The switch C is now free to be used in connection with other toll lines of the group to which it is common.
- The release of relay 412 also opens the energizing circuit for relay 413 which thereupon restores, in turn opening the energizing circuit for relay 501. The latter relay releases to remove ground from the windings of relay 510 through the wiper 502. Relay 510 releases for an instant but does not remain released sufficiently long to permit slow-to-release relay 509 to open its contacts. When relay 501 releases a connection is established from ground through the middle contact of relay 509, right-hand winding of relay 510, wiper 502, the normal contact of relay 501, and the contact and winding of stepping magnet 500 to grounded battery. The closure of this circuit causes stepping magnet 500 to step the wipers of the switch E from the terminals with which they are engaged to the next succeeding terminals individual to another line register. If this register is busy, the ground at the middle contact of relay 509 thereof will cause switch E to again be stepped. This action continues until a terminal is encountered by wiper 502 which is free from ground. If all the line registers are busy, the wipers of switch E will be stepped to the last terminals. Then upon the next operation of relay 413, a circuit for stepping magnet 500 will be closed from ground through the contact of relay 413, wiper 502 and the last terminal engaged thereby, the normal contact of relay 501 and the contact and winding of stepping magnet 500 to battery. This circuit is in shunt of relay 501, and hence

- stepping magnet 500 will operate to step the wipers of switch E from the last terminal to the first terminal to which a line register is connected. If this line register is idle, 5 then the stepping magnet will no longer have a circuit closed therefor through the wiper 502 and this magnet will come to rest. The relay 501 will then energize with the results previously described.
- 10 When the wiper 502 is moved from the terminal connected to the windings of relay 510 to preselect another line register, the windings of relay 510 are connected differentially and said relay thereupon releases.
- 15 The release of the latter relay opens the energizing circuit for relay 509 which, after an interval, restores to normal. The opening of the inner contact of relay 509 removes ground from the locking circuit of all the 20 transfer and register relays of the line register and also from the winding of relay 511, whereupon all of these relays which have been operated are released and the line register is thereupon in condition for use with 25 other calls.

When relay 328 energized the same opened at its normal contact the circuit for relay 419 which extended through the outer alternate contact of relay 326 and resistance 327. 30 Relay 419 releases and by closing its contact prepares a circuit for the stepping magnet 417 of switch F so that said switch and the sending distributor SD may function in connection with the transmission of signals for 35 other toll lines, the stepping circuit for said magnet being closed when the common conductor connected to the winding of relay 415 is grounded to energize this relay.

Referring again to the energization of the 40 transfer relay 912 at the termination of the transmission of the eight series of impulses for the call indicator relays, it will be seen that the removal of battery from the lower normal contact of relay 912 opens the locking circuit for relay 900 which thereupon restores. Relay 839 which was energized through the right-hand contact of relay 900 also releases upon the energization of relay 912. The first group of transfer relays 836, 50 841 and 842 are also released when relay 912 is operated due to the opening of the locking circuit of transfer relays at the lower normal contact of relay 912. The receiving mechanism RD including the locking and pyramid relays is now in normal condition 55 and ready to receive impulses in connection with other calls.

The energization of relay 912 furthermore 60 closes a circuit extending from grounded battery, through the alternate contact of said relay, and the windings of relays 916, 915 and 914 to ground. These relays energize to close circuits for the various call indicator lamps to be lighted. With relays

1000 and 1001 of the group assigned to the 65 lamps which indicate the first office designation operated, a circuit is established for the lamp WXY extending from grounded battery, through the inner left-hand contact of relay 914, lamp WXY, the lower alternate 70 contact of relay 1000, upper normal contact of relay 1003, lower normal contact of relay 1002, upper alternate contact of relay 1001, and the contact of relay 913 to ground. The lamp WXY is lighted in this circuit. In 75 the second group of relays, relay 1006 is operated. The energization of relay 914 thereof, closes a circuit to light the lamp ABC, which circuit extends from grounded battery, through the outer right-hand contact of relay 914, lower normal contact of relay 1005, lower alternate contact of relay 1006, middle normal contact of relay 1007, lamp ABC, upper alternate contact of relay 1006, lower normal contact of relay 1007, 80 upper normal contact of relay 1004, and the inner right-hand contact of relay 914 to ground. In the third group representing the last office designation, relay 1009 is operated. 85 Upon energization of relay 915 a circuit is therefore established to light the lamp JKL, said circuit extending from grounded battery through the inner left-hand contact of relay 915, lamp JKL, lower normal contact of relay 1008, upper normal 90 contact of relay 1011, lower normal contact or relay 1010, upper alternate contact of relay 1009, and the contact of relay 913 to ground. The energization of relay 915 and another similar relay (not shown) control 95 the lighting of the four lamps representing the numerical digits of the wanted line. The energization of relay 916 establishes a circuit to light the lamp M representing the 100 station designation, said circuit being traceable from grounded battery, through the right-hand contact of relay 916, lower alternate contact of relay 1013, lamp M, upper alternate contact of relay 1015, normal contact of relay 1014, upper alternate contact of 105 relay 1013, and the contact of relay 913 to ground. The eight lamps indicating the 110 office, number and station designations of the called line are now lighted before the incoming operator.

115 It will be obvious that if the called subscriber is not on a party line none of the last group of register relays 626, 627, 630 and 631 will be operated and therefore, the first four impulses of the eighth series transmitted to the receiving distributor RD will be of positive polarity and none of the relays 804 to 807 will be operated, with the result that none of the relays 1012 to 1015 will be energized. The transfer relays 910 to 912 will nevertheless be operated in the 120 same manner as previously described so that upon energization of the relay 912, the cir-

cuits for the office and number lamps will be closed to light these lamps.

Connection of toll switch trunk H to called subscriber's line.

- 5 The incoming operator upon observing the number of the wanted line communicates with the toll switching trunk operator over an order wire (not shown) to secure an 10 assignment of a toll switching trunk. The toll switching operator then informs the incoming operator that the toll switching trunk H should be employed for extending the connection to the subscriber's line circuit J. The incoming operator also informs 15 the toll switching operator of the number of the wanted line whereupon the latter operator inserts the plug 722 of the toll switching trunk H into the jack 723 of the called line. A circuit is thereupon established 20 extending from grounded battery through the winding of relay 724, sleeve contacts of jack 722 and plug 723, and the winding of cut-off relay 725 to ground. Relays 724 and 725 25 operate in this circuit. The energization of the latter relay disconnects the line relay 726 from the subscriber's line circuit J so that said line relay will not operate upon 30 response of the called subscriber, and will, therefore, prevent the lighting of the line signal 727. The energization of relay 724 establishes a circuit for lighting the lamp 728 extending from grounded battery through the lamp 728, the right-hand alternate contact of relay 724, resistance 729 35 and the normal contact of relay 730 to ground. The energization of relay 724 also disconnects the usual operator's telephone circuit testing equipment from the tip conductor of the trunk circuit with which a 40 test is made by placing such tip conductor in contact with the sleeve of jack 723 prior to the insertion of the plug 722. The closure of the left-hand alternate contact 45 of relay 724 completes the continuity of the tip conductor.

Incoming operator connects toll line L to the toll switching trunk circuit H.

- 50 The incoming operator now inserts the plug 731 in the jack 732, whereupon a circuit is established extending from grounded battery through the winding of relay 733 and the sleeve contacts of plug 731 and jack 55 732 to ground. The energization of relay 733 in this circuit establishes a circuit extending from grounded battery through the contact of relay 733, the alternate contact of relay 710 and the winding of relay 913 60 to ground. Relay 913 operates and in so doing removes ground from the locking circuits of the transfer relays 901 to 912, and also from the relays 1000, 1001, 1006, 1009, 1013 and 1015 with the result that all of

these relays restore to normal. The release 65 of relay 912 removes battery from the windings of relays 914, 915 and 916, whereupon these relays also release. The call indicator is now in its normal condition and ready 70 for another operation.

The operation of relay 733 also closes an obvious energizing circuit for relay 707 which, in opening its lower normal contact, opens the circuit for lamp 706 which is thereupon extinguished. Lamp 711 may be 75 extinguished by the operation of relay 707 or by the restoration of the assignment key 708 by the incoming operator at the time she receives the assignment of the toll switching trunk H and plugs into the jack 732. The energization of relay 707 disconnects the operator's testing equipment from 80 the line and completes the continuity of the tip conductor. The operation of relay 707 also opens the locking circuit of relay 701 which thereupon restores to again associate conductor 700 with the left-hand winding 85 of the differential relay 702. Relay 707 also establishes a circuit extending from grounded 90 battery through the left-hand winding of relay 730, the continuity contacts of relay 734, the upper left-hand winding of repeating coil 735, the tip contacts of jack 732 and plug 731, the upper alternate contact 95 of relay 707, the upper normal contact of relay 736, the upper right-hand winding of repeating coil 737, the winding of the supervisory relay 721, the left-hand contact 100 of relay 702, the lower right-hand winding of repeating coil 737, the lower normal contact of relay 736, ring contacts of plug 731 and jack 732, the lower left-hand winding of the repeating coil 735, the inner left-hand normal contact of relay 734 and the right-hand winding of relay 730 to ground. Relays 721 and 730 operate in this circuit and the energization of the latter relay extinguishes guard lamp 728.

The operation of the supervisory relay 721 establishes an energizing circuit for the slow-to-operate-and-release relay 720, said circuit extending from grounded battery through the winding of relay 720, the alternate contact of relay 721 and the right-hand alternate contact of relay 702 to ground. A circuit is also established for relay 714 by the energization of relay 721, said circuit being traceable from grounded battery through the winding and right-hand continuity contacts of relay 714, the left-hand contact of relay 713, the outer right-hand normal contact of relay 712, the normal contact of relay 709 and from thence over the energizing circuit for relay 720. Relay 714 being slow to operate, a circuit will also be established for relay 716 before the left-hand continuity contacts of relay 714 are opened. The circuit for relay 716 extends from 110 115 120 125

grounded battery through the winding of relay 840, the inner right-hand contact of relay 713, the winding and continuity contacts of relay 716, the left-hand continuity contacts of relay 714 and thence over the energizing circuit for relay 714. Relay 716 locks through its right-hand alternate contact while relay 714 locks through its right-hand alternate contact, the normal contact 10 of relay 715, the outer normal contact of relay 712 and from thence over the energizing circuit for relay 714. As previously described, the closure of the inner left-hand contact of relay 716 causes the energization 15 of relay 718 which prepares a circuit for relay 717, the latter relay operating when relay 716 releases.

The relay 840 operates in the circuit described for relay 716 to initiate the operation 20 of the sending mechanism SD' in the same manner as previously described, whereupon the same code of impulses is transmitted over the common signaling path P to effect the operation of the receiving distributor RD' 25 at the outward office. This code of impulses causes negative 120 volt current to be momentarily connected to conductor 322 and extending through the left-hand winding of relay 312 to energize this relay, whereupon 30 the same is locked as previously described. At the time this impulse is transmitted to relay 312, relay 311 is energized due to the previous release of relay 312 and relay 320 will be unaffected by this impulse. The energization 35 of relay 312 establishes a circuit extending from ground through the normal contact of relay 320, the left-hand alternate contact of relay 312, the right-hand alternate contact of relay 323, which is energized at 40 this time, the inner right-hand alternate contact of relay 305, the outer alternate contact of relay 303, resistance 306 and from thence over a previously described circuit through the winding of marginal relay 202. This 45 latter relay now energizes due to the inclusion of resistance 306 in multiple with the windings of relay 301 and thereby establishes a circuit extending from ground through the contact of relay 202, the right-hand alternate 50 contact of relay 206 and the guard lamp 222 to grounded battery. Lamp 222 is lighted to indicate to the outward operator that the toll line L has been extended to the called 55 subscriber's line and that she may now actuate her ringing key 221.

At the time the sending distributor SD' was transmitting the code of impulses to the outward office, relay 713 is again operated in the same manner as previously described to open the locking circuit of relay 716, which relay then releases. Relay 714, however, remains energized. The removal of ground from the inner left-hand contact of relay 716 permits relay 717 to operate in series with relay 718.

The outward operator actuates ringing key in cord circuit A.

The outward operator upon observing the lighted condition of lamp 222 actuates the 70 ringing key 221 and thereby connects ringing current from a suitable source through the lower alternate contact of key 221, the ring contacts of plug 203 and jack 300, the outer left-hand alternate contact of relay 75 305, the lower left-hand winding of repeating coil 329, condenser 330, winding of ringing response relay 331, the upper left-hand winding of coil 329, the inner left-hand alternate contact of relay 305, the tip contacts of jack 300 and plug 203, the alternate contact of relay 204, the left-hand normal contact of relay 207 and the upper alternate contact of key 221 to ground. Relay 331 80 energizes in this circuit to establish an obvious operating circuit for relay 319. The operation of the latter relay causes the energization of relay 315 over a circuit extending from grounded battery through the outer normal contact of relay 317, the contact of relay 316, winding of relay 315, the left-hand contact of relay 319 and the alternate contact of relay 310 to ground. Relay 315 85 operates and locks through its inner left-hand contact. When the outward operator releases the key 221, relay 331 releases and causes the restoration of relay 319. The operation of relay 315 and release of relay 319 initiates, in the same manner as previously described, the operation of 90 the sending mechanism including the switch F and the sending distributor SD. If, since the last operation of the sending distributor in transmitting the code impulses for the call indicator, the switch F had been operated by the seizure of another toll line, said switch will again be stepped to the terminal individual to line L by the energization of relay 415 in response to the operation of relay 315. The wipers of switch F 95 will be brought to rest in the same manner as previously described and the code of impulses for line L will thereupon be transmitted to the receiving distributor RD. As before, the negative 120 volt current will 100 then be momentarily connected to the conductor 700 and this impulse of current will be extended to ground through the right-hand winding of differential relay 703 to 105 energize this relay. This impulse of current is also passed through the left-hand winding of relay 702 but has no effect upon this relay since the same is already energized and locked. Upon energizing, relay 703 locks in a circuit extending from grounded 110 battery through its left-hand winding and contact and the contact of relay 704 to ground. The opening of the normal contact of relay 703 opens the energizing circuit for relay 704 but the latter relay 115 120

28

very slow in releasing and, therefore, will maintain its contact closed for an appreciable interval. The operation of relay 703 establishes a circuit for the slow-operate-and-release relay 705, said circuit extending from grounded battery through the winding of relay 705, and the right-hand alternate contacts of relays 703 and 702 to ground. Relay 705 energizes after which the contact of relay 704 opens and relay 703 releases. The release of relay 703 opens the energizing circuit for relay 705, but this relay being slow to release will maintain its contacts closed for an interval after its energizing circuit is open. The operation of relay 705 causes the energization of slow-to-release relay 738 over an obvious circuit and the latter relay in turn closes an obvious operating circuit for the slow-to-release relay 739. The operation of relay 738 also establishes an energizing circuit for the ringing relay 736, whereupon this relay energizes. Due to the slow-release nature of relays 705 and 738, relay 736 will be maintained operated for an appreciable length of time after the release of relay 703. During the operation of relay 736, a circuit is completed from the source of ringing current through the lower alternate contact of relay 736, the ring contacts of plug 731 and jack 732, the lower left-hand winding of repeating coil 735, the winding of the ringing response relay 740, condenser 741, the upper left-hand winding of the repeating coil 735, tip contacts of jack 732 and plug 731 and the upper alternate contacts of relays 707 and 736 to ground. Relay 740 operates in this circuit to establish an energizing circuit for the ringing relay 742, said circuit being traceable from ground through the contact of relay 740, the winding of relay 742 and the left-hand winding of relay 734 to grounded battery. Relays 734 and 742 operate in this circuit and the energization of the former opens the original energizing circuit for relay 730, but this relay is maintained energized through the alternate contact of relay 734. The operation of relay 742 closes a circuit extending from the source of ringing current through the upper alternate contact of said relay, the ring contacts of plug 722 and jack 723, the substation apparatus at J, the tip contacts of jack 723 and plug 722, the left-hand alternate contact of relay 724 and the lower alternate contact of relay 742 to ground. The called subscriber's bell is operated in this circuit to signal the subscriber that a call is to be answered.

60 During the operation of relay 736 the circuit for relay 721 through normal contacts of relay 736 is opened and relay 721 releases. In so doing, the locking circuit for relay 714 is opened and this relay restores. 65 As soon as relays 705 and 738 are restored to normal, relay 736 releases to disconnect the ringing current from relay 740 which thereupon releases to prevent further application of ringing current to the called line. When relay 734 restores in response to the removal of ground from the contact of relay 740, relays 730 and 721 are again energized over the original circuit described therefor. The operation of relay 721 again closes the original energizing circuit for relay 720 to maintain this relay in its operated condition, it having been held operated during the release of relay 721 by the energization of relay 739. Relay 720 being slow to release, the interval between the release of relay 739 and the energization of relay 721 is not sufficient to permit the release of relay 720. While the supervisory relay 721 is released during ringing and relay 720 is operated, a circuit is established for slow-release-relay 743 extending from grounded battery through the winding of relay 743, the alternate contact of relay 720, the normal contact of relay 721 and the right-hand alternate contact of relay 702 to ground. Relay 743 energizes but its operation has no effect upon the system at this time. The foregoing operation in response to the actuation of ringing key 221 is repeated each time said key is depressed to operate the called subscriber's bell.

The subscriber at substation J removes the receiver from its switch hook.

In response to the operation of the signal at the called substation, the subscriber thereat removes his receiver from his switch hook, thereby establishing a circuit for the supervisory relay 744 extending from grounded battery through the winding of relay 744, the upper right-hand winding of repeating coil 735, the upper normal contact of relay 742, the ring contacts of plug 722 and jack 723, the substation apparatus, the tip contacts of jack 723 and plug 722, the left-hand alternate contact of relay 724, the lower normal contact of relay 742 and the lower right-hand winding of repeating coil 735 to ground. Relay 744 operates and thereby establishes a circuit for relay 734 extending from grounded battery through the left-hand winding of relay 734, the contact of relay 744, the right-hand winding of relay 734 and the alternate contact of relay 730 to ground. Relay 734 operates to again maintain the energization of relay 730, but in its operation opens the circuit for the supervisory relay 721 which thereupon releases. The relay 739 having released at this time, the opening of the alternate contact of relay 721 permanently opens the circuit for the relay 720 which, after an interval, opens its alternate contact and closes its continuity contacts. The previously described circuit for relays 840 and 712, through the contacts of relays 713, 716, 717, 719, 720 and 721, is

- thereupon established and said relays energize to again effect the transmission of a code of impulses from the sending mechanism SD' to the receiving mechanism RD' in the same 5 manner as previously described. It will be recalled that the code transmitted when relay 712 is operated contains a final impulse of negative polarity which causes the energization of relay 809 in the mechanism RD'. 10 This connects positive 120 volt battery to the conductor 322 and this current passing through the left-hand winding of relay 312 causes the same to release. The opening of the left-hand contact of relay 312 breaks the 15 circuit through the resistance 306 and winding of marginal relay 202, whereupon this relay releases to open the circuit for the lamp 222. The lamp 222 is extinguished to inform the outward operator that the called 20 subscriber has answered and the operator will, therefore, no longer actuate the ringing key.

When relay 712 is operated the circuit for relays 717 and 718 is opened at the inner right-hand normal contact of relay 712 and relays 717 and 718 release. During the rotation of the sending distributor of the mechanism SD', relay 718 is energized, as previously described, to open the energizing 30 and locking circuit for relay 712, which relay thereupon restores. The restoration of differential relay 312, in response to the impulse of positive polarity, again establishes a circuit for relay 311 to disconnect the left-hand winding of differential relay 320 from the conductor 322.

The toll switching operator inserts the plug of toll switching trunk H into a busy flash jack.

If at the time the toll switching operator tests line J, before inserting the plug 722 into jack 723, and finds the line busy, she then inserts said plug into a busy flash jack 45 (not shown), which may be of any construction well known in the art. The insertion of the plug into this jack connects ground through an interrupter, the ring contacts of said jack and plug 722, the upper normal 50 contact of relay 742, the upper right-hand winding of repeating coil 785 and the winding of supervisory relay 744 grounded battery. The operation of relay 744 produces the same effect as described in connection 55 with the operation of this relay when the subscriber at substation J removed his receiver from its switch hook. The result of this operation is the transmission of a code of impulses to the receiving mechanism at 60 the outward office which causes the relay 312 to release and the lamp 222 to be extinguished. It will be recalled that in this operation the supervisory relay 721 releases. When the supervisory relay 744 releases in 65 response to the action of the interrupter in

the busy flash jack, relay 734 releases and again closes a circuit for the supervisory relay 721 in series with relay 730. The operation of relay 721 establishes a previously described circuit for relays 840 and 716 70 through contacts 713, 714, 712, 709, 721 and 702 to energize relays 840 and 716 in parallel with the relay 720. Relay 714 also energizes and locks, as previously described. The energization of relay 716 causes relay 75 718 to operate and prepare a circuit for relay 717 so that this latter relay will operate upon the energization of relay 713 as previously described, which results in the deenergization of relay 716, relay 714, 80 however, remaining in its locked condition. The energization of relays 840 and 716 results in the transmission of a code of impulses to the outward office in the same manner as previously described, whereupon 85 an impulse of negative polarity will be connected to the conductor 322 to again operate relay 312. Lamp 222 is thereupon lighted and relay 311 is released. When relay 716 releases in response to the energization of relay 713 during the transmission of the code of impulses to light the lamp 222, relay 717 operates and this relay, together with relay 718, remains operated 90 through contacts of relays 712 and 702. 95

When the interrupter in the busy flash jack next causes supervisory relay 744 to again operate, relay 721 releases to cause the restoration of relay 714, but relay 720 remains operated since it is slow in releasing. 100 Upon the next operation of relay 721, relays 714, 716 and 840 again operate, as previously described, and the energization of relay 716 then establishes a circuit for relay 715 extending from grounded battery through the winding and continuity contacts of this relay, the left-hand alternate contact of relay 717 and the inner left-hand contact of relay 716 to ground. Relay 715 energizes and locks through its winding and inner alternate contact, the inner normal contact of relay 712 and the right-hand alternate contact of relay 702. The energization of relay 715 establishes a locking circuit for relay 714 extending through 105 the winding and right-hand alternate contact of relay 714, the middle alternate contact of relay 715, and from thence to ground over the locking circuit of the latter relay. The maintenance of relay 714 in its 110 operated position prevents any further operation of relay 716 in response to subsequent operations of relay 721 while the plug 722 is inserted in the busy flash jack. The second operation of relays 840 and 716 causes 115 the transmission of another code of impulses similar to the first code to the outward office. An impulse of negative polarity is again connected to the conductor 322 and extended through the left-hand winding of re- 120

125

130

lay 312 to ground. This relay is already energized and, therefore, this impulse has no effect thereupon. The momentary impulse is also extended through the contact of relay 311, which is now released, and the left-hand winding of relay 320 to ground. This negative impulse causes relay 320 to energize and lock in a circuit extending from grounded battery through the right-hand 10 contact and winding of relay 320, and the alternate contact of relay 310 to ground. The energization of relay 320 connects the busy back interrupter 332 to the circuit including the resistance 306 and marginal relay 202, and causes said relay to repeatedly operate and release, whereby the lamp 222 is intermittently flashed. The flashing of this lamp serves to indicate to the outward operator that the line requires supervision, 20 and upon connecting her head set to the cord circuit A she will receive an audible busy signal.

Outward operator releases connection.

25 The outward operator thereupon proceeds to release the connection by removing the plug 203 from the jack 300. This causes the release of relay 201 followed by the de-energization of relays 204, 205 and 206, thus 30 restoring the cord circuit to its normal condition.

Relay 301 and the signal 302 are also released by the removal of plug 203 from jack 300. The release of relay 301 opens the holding circuit for relay 304, which thereupon restores. The opening of the contact of relay 301 also removes ground from the locking circuits of relays 303, 305 and 309, and these relays thereupon release. The 40 restoration to normal of relay 305 opens the holding circuit for relay 310, which thereupon releases to establish an energizing circuit for relay 314 extending from ground through the normal contact of relay 310, the outer contact of slow release relay 313, the winding of relay 314, and the inner normal contact of relay 317 to grounded battery. Relay 314 operates and locks through its inner left-hand alternate contact. The locking 45 circuits for relays 313 and 318 are thereupon opened and these relays release. The energization of relay 314 establishes a circuit for relay 415 of the sending distributor mechanism, said circuit extending from 50 grounded battery through the winding of relay 415, the inner normal contact of relay 319, and the right-hand alternate contact of relay 314 to ground. Assuming that the sending distributor SD had been employed 55 with other toll lines since the transmission of the last code of impulses therefrom, the energization of relay 415 again causes the stepping magnet 417 to operate, as previously described, to step the wipers of 60 switch F over the terminals until wiper 416

engages the associated terminal individual to line L. A circuit will thereupon be established for relay 418 extending from grounded battery through the left-hand winding of relay 418, wiper 416, the outer right-hand contact of relay 319, the outer left-hand alternate contact of relay 314, and the winding of relay 457 to ground. The energization of relay 418 in this circuit causes the wipers of switch F to come to 70 rest on the terminals individual to line L and also closes the previously described circuit for start magnet 433. Relay 457 also operates in the circuit described for relay 418, whereupon a previously described energizing circuit for relay 449 is established and this relay locks. The closure of the 80 right-hand alternate contact of relay 449 connects battery of negative polarity to the segment 448 of the sending distributor SD, which now operates to transmit a code of impulses to the receiving mechanism at the inward office. While the distributor is revolving, relay 441 operates to energize relay 317 over the previously described circuit. 90 Relay 317 energizes to open the locking circuit of relay 314, which thereupon releases. Relay 317 releases when relay 441 restores.

The release of relay 310, as previously described, also removes ground from the locking circuits of the differential relays 312 and 320, and from the holding circuits of relays 323, 325 and 328 and these relays thereupon release. After the code of impulses has been transmitted by the sending distributor SD and relay 314 releases in response to the energization of relay 317, followed by the release of the latter relay when the sending distributor has completed its 100 revolution, the apparatus of Fig. 3 is then 105 in normal condition.

The code of impulses now transmitted by the sending distributor is the same as that described in connection with transmission 110 of a code from the mechanism SD, when the relay similar to 457 therein is operated, and upon this code of impulses being received by the receiving distributor, relays 806, 808 and 809 are operated in a manner which is now believed to be obvious. The operation 115 of these three relays, together with the energization of pyramid relays 812 and 813, causes a momentary impulse of positive 120 volt current to be connected to the conductor 700, and from thence through the left-hand winding of relay 702 to ground. Relay 702 is released by this impulse of positive polarity. The removal of ground from the 125 right-hand alternate contact of relay 702 opens the locking circuits for relays 714, 715, 717 and 718, and these relays thereupon restore. The opening of the left-hand contact of relay 702 breaks the circuit for the 130 supervisory relay 721, which thereupon re-

- leases to permanently open the energizing circuit of relay 720, which extended through the alternate contact of relay 721 and the right-hand alternate contact of relay 702.
- 5 Relay 720, which has been energized during the interval of the transmission of impulses to the outward office to effect the flashing of lamp 222, but which performed no useful function during this interval, is now released.
- 10 By the release of relay 702 and consequent deenergization of the supervisory relay 721, guard lamps 706 and 728 are simultaneously lighted to give the inward and toll switching operators the disconnect signal. Lamp 706 is lighted over a circuit extending from grounded battery through the lamp 706, the lower alternate contact of relay 707, and the normal contact of relay 702 to ground. The opening of the circuit for the supervisory relay 721 also causes the release of relay 730, which is in series with said supervisory relay. The previously described lighting circuit for lamp 728 through the resistance 729 is thereupon established.

15 In response to the lighting of lamp 706, the inward operator removes plug 731 from jack 732 and thereby causes the release of relay 733, which removes battery from the winding of relay 707 to restore this relay to normal.

20 The toll switching operator, observing the lighted condition of lamp 728, removes the plug 722 from jack 723 to release relays 724 and 725. The release of relay 707 opens the lighting circuit for lamp 706 and this lamp is then extinguished. Restoration of relay 724 opens the circuit of lamp 728, which is thereupon extinguished. The apparatus of 25 the toll switching trunk is now in normal condition.

Subscriber at substation J, after answering call, recalls the outward operator.

- 30 Should the subscriber at substation J, after removing his receiver from its switch hook, desire to converse with the outward operator, he may signal this operator by repeatedly depressing and releasing the switch hook. The supervisory relay 744 responds to this operation of the switch hook in the same manner as described in connection with the insertion of plug 722 in the busy flash jack. Relay 721 also operates in the 35 same manner as described in this connection and this again results in two operations of the relay 716, whereby two codes of impulses are transmitted to the outward office to operate in succession the relays 312 and 320, which results in the flashing of the lamp 222.

40 Should the subscriber, after repeatedly working his switch hook up and down, keep his receiver off the switch hook, the supervisory relay 744 will remain operated and

the supervisory relay 721 will release. During the operation of the switch hook relay 720 is operated to establish a previously described circuit for relay 743 through the normal contact of relay 721 and the right-hand alternate contact of relay 702. Upon the permanent restoration of relay 721 when the subscriber stops operating the switch hook, the circuit for relay 720 is opened and this relay, after an interval, releases to open the energizing circuit of relay 743. When relay 743 restores a circuit is established for relay 712 extending from grounded battery through the winding of relay 840, the outer right-hand contact of relay 713, the winding of relay 712, the right-hand normal contact of relay 716, the right-hand contact of relay 717, which is energized at this time, the right-hand contact of relay 709, the outer alternate contact of relay 715, which is also energized at this time, the continuity contacts of relay 743, and the right-hand alternate contact of relay 702 to ground. Relay 712 energizes and locks, as previously described, and the operation of this relay opens the circuits for relays 715, 717 and 718, which relays thereupon release. In the same manner as formerly described, the operation of relay 712 causes the transmission of a code of impulses to the receiving mechanism at the outward office, which results in the connection of a positive impulse to the conductor 322. Relays 312 and 320 both being energized at this time, this positive impulse, through the left-hand windings of said relays, cause the same to release and thereby disconnect the interrupter 332 from the circuit including relay 202. The lamp 222 is thereupon extinguished. While this lamp is flashing the outward operator in response thereto may supervise the connection by connecting her head set to the cord circuit A, whereupon she may converse with the called subscriber.

45 After repeatedly operating the switch hook, should the subscriber at substation J then replace the receiver upon said switch hook, a code of impulses, following those which cause the flashing and extinguishment of lamp 222, will be transmitted to the outward office to again light this lamp to give the outward operator the disconnect signal. When the receiver is replaced at the substation J, relay 744 releases to cause the energization of relay 721. Relays 840, 714 and 716 are thereupon operated, as previously described, to effect the transmission of the code of impulses to the outward office, which results in the connection of an impulse of negative polarity to the conductor 322. When relays 312 and 320 released in response to the positive impulse transmitted over the conductor 322, when relay 712 energized, relay 311 again operated to disconnect the relay 320 from the conductor

322. Therefore, when this last negative impulse is transmitted over conductor 322, only the relay 312 will respond thereto. The energization of this latter relay again causes lamp 222 to be lighted and the outward operator, observing the condition of the lamp, removes the plug 203 from jack 300, with the previously described results. The disconnect signal is transmitted to the outward operator in a manner which will now be understood when the subscriber at substation J replaces his receiver upon its switch hook at the termination of the conversation.

15 When supervisory relay 721 operated to cause the energization of relay 716, relay 718 operated, and when relay 716 released, due to the energization of relay 713, relay 717 operated. Relays 714, 717 and 718, therefore, remain energized until the code of impulses is transmitted from the sending distributor SD to connect positive current to the conductor 700, which results in the release of relay 702 and consequent release of relay 721. Relays 714, 717 and 718 will then restore to normal.

What is claimed is:

1. In a telephone system, two distant offices, a plurality of transmission lines extending between said offices, a signaling path common to said transmission lines and interconnecting said offices, a signal at one of said offices, a call indicator also at said office, and means for transmitting series of impulses over said common signaling path for operating said signal and call indicator.

2. In a telephone system, two distant offices, a plurality of transmission lines extending between said offices, a signaling path common to said transmission lines and interconnecting said offices, a signal at one of said offices, a call indicator also at said office, and means for transmitting a series of impulses over said signaling path for initially operating said signal and thereafter transmitting over said path other series of impulses for operating said call indicator.

3. In a telephone system, two distant offices, a plurality of transmission lines extending between said offices, a signaling path common to said transmission lines a signal at each of said offices, a call indicator at one of said offices, and means for transmitting series of impulses over said common signaling path for operating said signals and said call indicator.

4. In a telephone system, two distant offices, a plurality of transmission lines extending between said offices, a signaling path common to said transmission lines, a signal at one of said offices, a call indicator also at said office, and means for transmitting a series of impulses over said signaling path for initially operating said signal and there-

after transmitting over said path other series of impulses modified with respect to the first series for operating said call indicator.

5. In a telephone system, two distant offices a plurality of transmission lines extending between said offices, a signaling path common to said transmission lines, a signal at one of said offices, a call indicator also at said office, and means for transmitting a series of impulses over said signaling path for initially operating said signal and thereafter transmitting over said path series of impulses modified with respect to each other and to the first-named series for operating said call indicator.

6. In a telephone system, two distant offices, a plurality of transmission lines extending between said offices, a signaling path common to said transmission lines, a signal at one of said offices, signal receiving equipment at the latter office controlled over said common path for causing the operation of said signal, a call indicator at said office and normally disconnected from said signal receiving equipment, means actuated upon the operation of said signal for connecting said call indicator to said signal receiving equipment, and means operable thereupon for transmitting series of impulses over said common path to said signal receiving equipment for operating said call indicator.

7. In a telephone system, two distant offices, a plurality of transmission lines extending between said offices, a signaling path common to said transmission lines, a signal and a call indicator at one of said offices, a register at the other office for controlling the operation of said call indicator, means for setting said register, and means for transmitting series of impulses over said signaling path for operating said signal and for thereafter transmitting over said path other series of impulses in accordance with the setting of said register for operating said call indicator.

8. In a telephone system, two distant offices, a plurality of transmission lines extending between said offices, a signaling path common to said transmission lines, a signal at each of said offices, a register at one office, means for setting said register, a call indicator at the other office, means for transmitting a series of impulses over said signaling path for operating the signal at one of said offices and for transmitting other series of impulses over said path to thereafter operate said call indicator in accordance with the setting of said register, and means for causing the transmission of another series of impulses over said path for operating the signal at the first-named office and for restoring said register.

9. In a telephone system, two distant offices, a plurality of transmission lines ex-

- tending between said offices, a signaling path common to said transmission lines, a signal and a call indicator at one of said offices, a register at the other office for controlling the operation of said call indicator, means for preselecting said register and associating the same with one of said transmission lines, means for setting said register over said transmission line, and means for transmitting series of impulses over said signaling path for operating said signal and for thereafter transmitting over said path other series of impulses in accordance with the setting of said register for operating said call indicator. 10
10. In a telephone system, two distant offices, a plurality of transmission lines extending between said offices, a signaling path common to said transmission lines, a signal at each of said offices, a plurality of registers at one office, means for preselecting one of said registers and associating the same with one of said transmission lines, means for setting said register over said transmission line, a call indicator at the other office, means for transmitting series of impulses over said signaling path for operating the signal at one of said offices and for transmitting other series of impulses over said path to thereafter operate said call indicator in accordance with the setting of said register, and means for causing the transmission of another series of impulses over said path for operating the signal at the first-named office and for restoring said register. 20
11. In a telephone system, two distant offices, a plurality of transmission lines extending between said offices, a signaling path common to said transmission lines, a signal and a call indicator at one of said offices, a register at the other office normally disconnected from said signaling path, means for setting said register, means for transmitting a series of impulses over said signaling path for operating said signal, means operable in response to the operation of said signal for transmitting another series of impulses over said path, and means responsive to the last-named series of impulses for associating said register with said path whereby series of impulses in accordance with the setting of said register are transmitted over said path to operate said call indicator. 30
12. In a telephone system, two distant offices, a plurality of transmission lines extending between said offices, a signaling path common to said transmission lines, a signal and a call indicator at one of said offices, a plurality of line registers at the other office, means for preselecting one of said registers, a plurality of link circuits for joining the preselected line register to one of said transmission lines, means for pre- 40
- selecting one of said link circuits, a switch operable upon seizure of said transmission line for completing the connection thereof to the preselected line register through said link circuit, means for thereupon setting said line register, and means for transmitting a series of impulses over said signaling path for operating said signal and for thereafter transmitting other series of impulses in accordance with the setting of said line register to operate said call indicator. 50
13. In a telephone system, outward and incoming offices, a plurality of transmission lines extending between said offices, a signaling path common to said lines, a signal and a call indicator at said incoming office, a register at said outward office operable to register the number of a wanted line, means for connecting said register to one of said transmission lines, a second register thereupon actuated in accordance with the operation of the first-named register, and means for transmitting a series of impulses over said signaling path for operating said signal and for transmitting over said path other series of impulses corresponding to the condition of the second-named register for controlling said call indicator. 60
14. In a telephone system, outward and incoming offices, a plurality of transmission lines extending between said offices, a signaling path common to said lines, a signal and a call indicator at said incoming office, a cord register at said outward office operable to register the number of a wanted line, a cord circuit for connecting said register to one of said transmission lines, a second register thereupon actuated in accordance with the operation of the first-named register, and means for transmitting a series of impulses over said signaling path for operating said signal and for transmitting over said path other series of impulses corresponding to the condition of the second-named register for controlling said call indicator. 70
15. In a telephone system, outward and incoming offices, a plurality of transmission lines extending between said offices, a signaling path common to said lines, a signal and a call indicator at said incoming office, a plurality of cord circuits at said outward office, a cord register also at said outward office operable to register the number of a wanted line, a line register, means for connecting said line register to one of said transmission lines, a switch common to said cord circuits and operable upon connection of one of them to said transmission line to transmit the condition existing at the operated cord register through said cord circuit to said line register whereby said condition is recorded thereat, and means responsive to the connection of said cord circuit with said transmission line for transmitting over said signaling path a series of impulses for oper- 80

ating said signal and for thereafter transmitting over said path other series of impulses corresponding to the condition of said line register for operating said call indicator.

16. In a telephone system, outward and incoming offices, a plurality of transmission lines extending between said offices, a signaling path common to said lines, a signal 10 and a call indicator at said incoming office, a plurality of cord circuits at said outward office, a cord register also at said outward office operable to register the number of a wanted line, a line register, means for connecting said line register to one of said 15 transmission lines, a switch common to said cord circuits and operable upon connection of one of them to said transmission line to

transmit the condition existing at the operated cord register through said cord circuit 20 to said line register whereby said condition is recorded thereat, and means responsive to the connection of said cord circuit with said transmission line and operable during the setting of said line register to transmit 25 over said signaling path a series of impulses individual to said transmission line to operate said signal and to transmit over said path other series of impulses in accordance with the setting of said line register after 30 the same has been operated.

In witness whereof, I hereunto subscribe my name this 12th day of August A. D., 1921.

HUGH D. MACPHERSON.
